SIGNALING SYSTEM

Clarence Ernest Lomax, Oak Park, Ill., assignor to
 Associated Electric Laboratories, Inc., Chicago,
 Ill., a corporation of Delaware

Application June 20, 1938, Serial No. 214,724

44 Claims. (Cl. 179—25)

The present invention relates to signaling systems and, more particularly, to switching apparatus for use in automatic telephone systems.

In an automatic telephone system, switching apparatus including a large number of switches is necessary for performing the various line switching functions required in establishing desired connections between the many lines of the system. Switches embodying several types of 5 switching units or mechanisms for performing the above-noted functions are known in the art. One improved form of switching unit which is well adapted for use in the application noted, and which possesses distinct advantages with respect 10 to the features of construction and mode of operation thereof, is disclosed and claimed in the pending application of Hans Sengebusch, Serial No. 214,722, filed June 20, 1938. Briefly described, this switching unit or mechanism is 15 adapted to be associated with a conductor bank formed of uninsulated conductors and comprises a plurality of elementary switches, each of which is selectively operative and includes two line selecting devices which are adapted to be operated 20 together in order to select simultaneously two lines in the conductor bank. Furthermore, the switching unit is so constructed and arranged that it may be incorporated in either a finder or selector switch, as desired. The form of switching unit noted is exceedingly compact and of 25 small size, is economical to manufacture and install, and may be readily incorporated in either of the types of switches noted.

It is an object of the present invention to provide a signaling system and, more particularly, an automatic telephone system comprising a plurality of switches embodying switching units of the form noted, and including improved apparatus for controlling the switching units, which 30 consists primarily of standard rotary switches and relays arranged in a simple manner such that a minimum amount of control apparatus is required for a system of a given size.

Another object of the invention is to provide, 35 in a system of the character described, an improved line selecting switch embodying a switching unit of the form noted and including improved apparatus for controlling the operation 40 of the switching unit.

A further object of the invention is to provide, 45 in an automatic telephone system, an impulse responsive line selecting switch embodying a switching unit of the form noted, and including 50 improved apparatus for controlling the automati-

c operation of the switching unit to select an idle line in a small group of lines.

It is a still further object of the invention to provide, in an automatic telephone system, an impulse responsive line selecting switch and improved impulsing apparatus for transmitting a plurality of series of impulses to the line selecting switch, thereby to control the operation thereof. 5

In general, the objects as set forth are attained 10 in accordance with the present invention by providing, in a telephone system of the character noted, switching apparatus comprising a conductor bank formed of uninsulated conductors and a plurality of finder-connector links, each 15 link including a finder portion or switch and a connector portion or switch, and each switch embodying a switching unit or mechanism of the form noted having access to each line in the conductor bank. The lines in the conductor bank 20 are arranged in a plurality of divisions, each division comprising two groups, each group comprising a plurality of subgroups, at least one subgroup including a small group of lines, and each subgroup including a plurality of lines. The 25 small group of lines of the conductor bank are adapted to be connected by way of line circuits, individual thereto, to P. B. X. lines extending to a private branch exchange; while the remainder of the lines in the conductor bank are adapted to 30 be connected by way of line circuits, individual thereto, to subscriber lines extending to subscriber substations. More specifically, each of the finder switches constitutes an impulse responsive 35 line selecting switch embodying a switching mechanism having access to each of the lines in the conductor bank, and having associated therewith an arrangement including a circuit for transmitting operating impulses to the switch, a stepping mechanism, means including a motor 40 for operating the stepping mechanism a plurality of steps, the steps being divided into a plurality of active and inactive groups, successive groups of active steps being separated from each other by a group of inactive steps, a circuit for energizing the motor, and means for controlling the 45 energizing circuit to cause the motor to operate the stepping mechanism the active steps at a relatively low speed and to operate the stepping mechanism the inactive steps at a relatively high 50 speed. This arrangement also includes means for transmitting by way of the first-mentioned circuit to the switch a plurality of series of operating impulses corresponding to the number of 55 groups of active steps the stepping mechanism

is operated, the number of impulses in each series corresponding to the number of steps the stepping mechanism is operated in the corresponding group of active steps, thereby to cause 5 the switching mechanism to select a corresponding line in a corresponding subgroup in the group of lines in the conductor bank.

In accordance with another feature of the invention, each of the connector switches constitutes 10 a line selecting switch comprising a trunk line, a switching mechanism of the form noted having access to each of the lines in the conductor bank, means including an impulse responsive motor for operating the switching mechanism, first and second circuits for energizing the 15 motor, and means for transmitting a plurality of series of impulses by way of the first circuit to the motor to cause the switching mechanism to select one line in the small group of lines in the 20 one subgroup in the one group of lines in the conductor bank. Further, this line selecting switch comprises means including a control relay for testing the idle or busy condition of a selected line in the small group of lines, the control 25 relay being operated in the event the selected one line in the small group of lines is busy, means responsive to the operation of the control relay for transmitting a single impulse by way of the second circuit to the motor to cause the switching 30 mechanism to select another line in the small group of lines, means responsive to the operation of the motor for causing the control relay to restore, the control relay remaining restored in the event the selected other line in the small group 35 of lines is tested idle, and means responsive to the test of an idle condition of the selected other line in the small group of lines for connecting the trunk line thereto. This line selecting switch also includes means responsive to the test of a 40 busy condition of the selected other line in the small group of lines for projecting busy tone current over the trunk line.

In accordance with a further feature of the invention, each line selecting switch comprises 45 a switching mechanism of the form noted, including a plurality of elementary switches individually associated with the divisions of lines in the conductor bank, means including a first operating member for selecting any one of the 50 elementary switches to be operated, thereby to select the two groups in the associated division of lines, means including a second operating member for causing a selected one of the elementary switches to select any two corresponding 55 subgroups in the two selected groups of lines, and means including a third operating member for causing the selected elementary switch to select simultaneously any two corresponding lines in the two selected subgroups of lines. Further, 60 each line selecting switch includes a first impulse responsive means for rendering successively operative the first, second and third operating members, a second impulse responsive means for selectively operating an operative one of the operating members, a circuit for controlling the impulse responsive means, and control apparatus for the circuit, the control apparatus being so constructed and arranged that during operation thereof a single control impulse is transmitted 65 by way of the circuit to the first impulse responsive means and a series of control impulses is thereafter transmitted by way of the circuit to the second impulse responsive means.

In accordance with a still further feature of the 70 invention, each line selecting switch comprises a

switching unit or mechanism of the form noted including a plurality of elementary switches and first, second and third operating members for causing the operation noted of a selected one of the elementary switches, each of the operating members having a normal and a plurality of off-normal positions corresponding, respectively, to idle and operated positions thereof, and means for moving the operating members in a predetermined order from their normal into their off-normal positions. Further, each line selecting switch includes a reset mechanism for moving the operating members in a different predetermined order from their off-normal back into their normal positions, a motor for operating 15 the reset mechanism, first and second circuits for energizing the motor, means for completing one of said circuits, means responsive to a predetermined operation of the reset mechanism for completing the other of the circuits, means responsive to the movement of at least one of the operating members back into its normal position for interrupting one of the circuits, and means responsive to another predetermined operation of the reset mechanism for interrupting 20 the other of the circuits.

Further features of the invention pertain to the particular arrangement of the circuit elements of the system whereby the above-outlined and additional operating features thereof are attained.

The novel features believed to be characteristic of the invention are set forth with particularity in appended claims. The invention, both as to its organization and method of operation, together with further objects and advantages thereof, will best be understood by reference to the following specification taken in connection with the accompanying drawings, in which Figure 1 is an end elevational view of the front and rear frames of a switching apparatus constructed and arranged in accordance with the present invention; Fig. 2 is a side elevational view of the front frame shown in Fig. 1; Fig. 3 is an enlarged side elevational view, partly in section, 45 of a particular structural detail of the front frame, taken in the direction of the arrows 3 in Fig. 1; Fig. 4 is an enlarged sectional view of the particular structural detail of the front frame, taken along the line 4-4 in Fig. 2; Fig. 5 is 50 an enlarged fragmentary end elevational view of the conductor bank and two of the switching units carried by the front and rear frames shown in Fig. 1; Figs. 6, 7 and 8, taken together, are a fragmentary plan view of one of the automatic 55 switching units of the switching apparatus; Fig. 9 is a plan view of one of the elementary switches embodied in the automatic switching unit illustrated, showing the elementary switch in an operated position; Fig. 10 is an end elevational view, 60 partly in section, of the operated elementary switch, taken along the line 10-10 in Fig. 9; Fig. 11 is a fragmentary side elevational view of a reset mechanism embodied in the switching unit illustrated, taken in the direction of the arrows 65 11-11 in Fig. 6; Fig. 12 is a sectional view of an element of the operating mechanism embodied in the switching unit illustrated, taken along the line 12-12 in Fig. 6; Fig. 13 is an enlarged fragmentary end elevational view of an escapement 70 mechanism embodied in the switching unit illustrated, taken in the direction of the arrows 13-13 in Fig. 7; Fig. 14 is an end elevational view of an escapement control mechanism embodied in the switching unit illustrated, taken in the di- 75

rection of the arrows 14-14 in Fig. 7; Fig. 15 is a sectional view of the escapement control mechanism, taken along the line 15-15 in Fig. 14; Fig. 16 is a sectional view of an indicator embodied in the switching unit illustrated, taken along the line 16-16 in Fig. 6; and Figs. 17, 18 and 19, taken together, illustrate the details of a complete automatic telephone system having incorporated therein the switching apparatus shown in Figs. 1 to 16, inclusive.

Referring now more particularly to Figs. 17, 18 and 19 of the drawings, there is illustrated an automatic telephone system comprising an exchange having extending thereto a plurality of subscriber lines and a group of P. B. X. lines, two of the subscriber lines and one of the group of P. B. X. lines being indicated, respectively, at 304, 670 and 705, and subscriber controlled switching apparatus for setting up connections between the various lines. In brief, the switching apparatus comprises a conductor bank 24 including a plurality of lines, each line including a number of bare uninsulated conductors, and a plurality of finder-connector links including the link 501, each link having access to each line in the conductor bank. The number of links in the system are determined in accordance with the maximum volume of traffic the exchange is required to handle. Each line is adapted to be connected by way of a line circuit individual thereto to a corresponding line in the conductor bank, and each finder-connector link comprises a finder portion or switch and a connector portion or switch connected together by a trunk line. Thus, the subscriber lines 304 and 670 and the P. B. X. line 705 are adapted to be connected by way of the line circuits 300, 675 and 740, respectively, to corresponding lines in the conductor bank 24, and the illustrated finder-connector link 501 comprises a finder switch 301 and a connector switch 500 connected together by a trunk line 325. More specifically, the exchange is designed to serve one thousand lines and the conductors in the conductor bank 24 are arranged in five divisions, each division comprising two groups, each group comprising ten levels or subgroups, each subgroup comprising ten lines, and each line comprising a positive, a negative and a control conductor. Distributor and common equipment is associated with each group of lines terminating at the exchange in order to assign the links to the use of the successive calling subscriber lines included in the associated group and to cause the finder switch of an assigned link to find a calling line, the distributor and common equipment associated with a group of lines including the subscriber line 304 being indicated at 302. Preferably, each of the distributors is of the fully directive type, having access to each link in the exchange and being operative immediately an assigned link seizes a calling line in the associated group to assign another idle link to the use of the next calling line in the associated group.

The end of each subscriber line, remote from the exchange housing the switching apparatus illustrated, terminates in a subscriber substation which may be of any desired arrangement. Two of such substations are diagrammatically illustrated at A and B associated with the subscriber lines 304 and 670, respectively. In brief, each of the substations may comprise the usual hand-set type of transmitter and receiver, a hook switch, a ringer and an impulsing device for transmitting the switch control impulses by way

of the associated subscriber line to the automatic switching equipment embodied in the line terminating exchange.

The end of each P. B. X. line, remote from the exchange housing the switching apparatus illustrated, terminates at the private branch exchange indicated at 700. The private branch exchange 700 includes the usual attendant's position which is provided with a transmitter, a receiver, an impulsing device for transmitting switch control impulses by way of any one of the P. B. X. lines to the automatic switching equipment embodied in the line terminating exchange and operator controlled switches for routing connections between the substation lines extending to the private branch exchange.

Each of the line circuits comprises a line relay and a cut-off relay, the line and cut-off relays illustrated at R350 and R340, respectively, being embodied in the line circuit 300, the line and cut-off relays illustrated at R650 and R660, respectively, being embodied in the line circuit 675, and the line and cut-off relays illustrated at R730 and R720, respectively, being embodied in the line circuit 740.

The distributor and common equipment associated with each group of lines may be identical with that illustrated at 302. In brief, the distributor and common equipment 302 comprises two rotary switches 465 and 485, an impulse sender circuit and a plurality of control relays R390, R400 and R410. The rotary switch 465 includes an operating motor M479 and two banks of contacts 467 and 478, having double ended wipers 466 and 477, respectively associated therewith, each wiper being rotatable over the associated contact bank into engagement with the individual contacts therein. The rotary switch 485 includes an operating motor M474 and four banks of contacts 487, 489, 491 and 493 having double ended wipers 486, 488, 490 and 492, respectively associated therewith, each wiper being rotatable over the associated contact bank into engagement with the individual contacts therein. The impulse sender circuit includes an impulse relay R415, a control relay R498 and a transfer relay R420.

The finder switch of each finder-connector link in the system may be identical to the finder switch 301. In brief, this finder switch comprises an automatic switching unit or mechanism, two switching relays R360 and R370, and a control relay R380. The automatic switching unit includes five elementary switches, each being provided with two sets of wipers associated with the conductor bank 24, the wiper sets of one of the elementary switches of the switching unit being indicated at 45^a to 50^a, inclusive. The automatic switching unit also includes a plurality of operating motors M1^a, M2^a and M3^a and a plurality of contact sets 222^a, 237^a, 245^a, 260^a, 270^a and 280^a, the construction and arrangement of the automatic switching unit being described in greater particularity subsequently.

The connector switch of each finder-connector link may be identical to the connector switch 500. In brief, this connector switch comprises an automatic switching unit or mechanism, a line relay R520, a hold relay R530, a battery reversing relay R550, a busy relay R570, a ring cut-off relay R580, a switching-through relay R590, a switching relay R600, and a plurality of control relays R540 and R560. Also the connector switch is provided with an arrangement for hunting idle P. B. X. lines, which includes a control

- relay R610. The automatic switching unit is of substantially the same construction as the automatic switching unit embodied in the finder switch 301 and includes five elementary switches, 5 each being provided with two sets of wipers associated with the conductor bank 24, the wiper sets of one of the elementary switches of the switching unit being indicated at 45^b to 50^b, inclusive. Also, the switching unit includes a plurality of operating motors M1^b, M2^b and M3^b, and a plurality of contact sets 222^b, 233^b, 237^b, 245^b, 10 270^b and 280^b.

Arrangement of the switching apparatus

- 15 Referring more particularly to Figs. 1 and 2 of the drawings, it will be observed that the switching apparatus includes front and rear frames 20 and 21, respectively, the frames being of similar construction and each comprising a 20 plurality of vertical and horizontal members 22 and 23, respectively, secured together in any suitable manner. The frames 22 and 23 are arranged back to back and secured together in spaced relation, the conductor bank 24 being arranged to occupy the space between the backs of the frames. The conductors in the conductor bank 24 extend in a vertical direction and, being uninsulated, serve both as multiple conductors between the automatic switching units and as 25 fixed wiper contacts for the movable wipers of the individual switching units. Also, each conductor is retained in position in its division by a plurality of spaced-apart insulating members 25. The positive, negative and control conductors in each division are segregated into three subdivisions which are arranged in the same manner. The line conductors in each subgroup in each subdivision are arranged in substantially the same vertical plane, each line conductor being 30 spaced from the adjacent line conductor by a fixed distance; and the levels or subgroups in each subdivision are arranged in substantially parallel vertical planes, each subgroup being spaced from the adjacent subgroup by a fixed 35 distance. The two groups in each division are so arranged that corresponding lines in each group are engaged simultaneously by two sets of wipers carried by the elementary switch associated with a division and included in the switching unit as 40 is more fully explained subsequently.

50 Each of the frames 20 and 21 is adapted to support a group of substantially identical automatic switching units in vertical alignment and in such a manner that each switching unit has 55 access to each line in the conductor bank 24. This is accomplished by providing the front frame 20 with a plurality of sets of supporting elements 26 and the rear frame 21 with a plurality of sets of supporting elements 27. In each 60 frame, each set of supporting elements is spaced in a vertical direction a fixed distance from the adjacent set of supporting elements and comprises two horizontally aligned supporting elements respectively secured to the vertical members 22 disposed at the right-hand and left-hand ends of the frame. In order to prevent the switching unit supported by the rear frame 21 from interfering with the switching units supported by the front frame 20, the sets of supporting elements 27 carried by the rear frame 21 are staggered in a vertical direction with respect to the sets of supporting elements 26 carried by the front frame 20. Thus, the switching units of one of the groups have access to sections 65 70 of the conductor bank 24 disposed between the

switching units of the other group, as illustrated in Fig. 5. Preferably, the group of switching units supported by one of the frames are embodied in the finder switches of the finder-connector links of the system, while the group of switching units supported by the other of the frames are embodied in the connector switches of the finder-connector links of the system, the corresponding finder and connector switches of each link being connected together by a trunk 10 line as previously explained. For example, the group of switching units supported by the front frame 20 may be embodied in finder switches, while the group of switching units supported by the rear frame 21 may be embodied in connector 15 switches.

Construction and operation of the switching units

Each of the switching units is of the construction of that described and claimed in the pending application of Hans Sengebusch, previously noted, and includes a base plate 28 which constitutes a shelf adapted to be supported upon one of the sets of supporting elements carried by 20 one of the frames. As best shown in Figs. 3 and 4, the opposite ends of the base plate 28 of one of the switching units supported in the front frame 20 rest upon the upper surfaces of the supporting elements of one of the sets of supporting elements 26. The base plate 28 is provided with an upstanding flange 29 extending along the front edge thereof which projects over the vertical members 22 disposed at the opposite ends of the front frame 20. The base plate 28 is secured in 30 place at each end thereof by an arrangement including a screw 30 extending through an elongated opening 31 formed in the flange 29 and threaded into an opening in the vertical member 22. Also, an arrangement is provided for 40 locking each end of the base plate 28 securely in place, which comprises a pair of screws 32 threaded in openings formed in the flange 29 and engaging the vertical member 22. The elongated openings 31 formed in the opposite ends of 45 the flange 29 accommodate adjustment of the switching unit in a longitudinal direction with respect to the ends of the front frame 20, and the screws 30 and 32 accommodate adjustment of the switching unit in a lateral direction with respect to the front and back of the front frame 20.

In placing a switching unit in the front frame 20, the base plate 28 of the switching unit is first positioned upon the set of supporting elements 26 disposed at the desired level. The switching unit is then slid laterally into place and adjusted so that the same is in proper alignment with respect to the conductor bank 24. The screws 30 are then inserted through the elongated openings 31 formed in the opposite ends of the flange 29 and tightened into snug engagement with the flange 29. The screws 32 are then tightened into snug engagement with the vertical members 22 disposed at the opposite ends of the front frame 20, thereby securely retaining the switching unit in its adjusted position. The switching unit may be removed from the front frame 20 by withdrawing the base plate 28 after the screws 30 have been untightened and removed.

Each automatic switching unit is provided with 70 an arrangement, more fully described subsequently, for indicating the idle or particular operated position thereof, which includes a signal visible through an aperture 33 provided in an escutcheon plate 34 secured to the flange 29. Also, an open-

ing 35 is formed in the flange 29 which is adapted to receive a plug in order to facilitate testing of the automatic switching unit.

Referring now to Figs. 6, 7 and 8, there is shown a fragmentary portion of one of the automatic switching units of the switching apparatus, which comprises five elementary switches of identical construction and respectively associated with the five divisions of lines in the conductor bank 24. The illustrated elementary switches 40 and 41, respectively, are associated with the first and fifth divisions of lines in the conductor bank 24, the first division comprising the first and second groups of ten levels or subgroups of lines each, and the fifth division comprising the ninth and tenth groups of ten levels or subgroups of lines each. Each of the elementary switches comprises a carriage 42 individually provided with an element or slide 43 mounted thereon, a contact controlling member 44 being mounted upon the slide 43. The contact controlling member 44 carries two lines selecting devices in the form of two sets of wipers, the first set of wipers being individual to the odd group in the associated division of lines, and the second set of wipers being individual to the even group in the associated division of lines. More particularly, the first set of wipers comprises the wipers 45, 46 and 47, which are adapted to engage the positive, negative and control conductors, respectively, of the lines in the odd group; while the second set of wipers comprises the wipers 48, 49 and 50, which are adapted to engage the positive, negative and control conductors, respectively, of the lines in the even group. Also, a terminal block 51 is mounted on the slide 43 in order to extend electrical connections to the two sets of wipers.

The carriage 42 of each elementary switch is mounted on a longitudinal guide bar 52 carried by the base plate 28, as best shown in Figs. 9 and 10. The rear edge of the carriage 42 is provided with a downwardly extending flange 53 which slidably engages a cooperating guide plate 54 individual thereto. The guide plate 54 is secured to an upstanding flange 55 provided on the rear edge of the base plate 28. Each of the carriages 42 has a normal position and is movable along a longitudinal path into ten off-normal positions respectively corresponding to the ten levels or subgroups in the odd and even groups in the associated division of lines in the conductor bank 24. The movement of the slide 43 on the carriage 42 is guided at the front edge of the slide by a screw 56 which rides in a slot, not shown, provided in the carriage 42, and at the rear edge of the slide by two downwardly extending lugs 57 formed thereon which cooperate with two guide arms 58 provided on the carriage 42. Each of the slides 43 has a normal position and is movable along a lateral path into ten off-normal positions respectively corresponding to the ten lines in each level or subgroup in the odd and even groups in the associated division.

An arrangement including a hundred bar 59, a ten bar 60 and a unit bar 61 is provided for operating the elementary switches of the switching unit. These operating bars are common to the elementary switches and disposed in superimposed relation, the hundred bar 59 being the top bar and the unit bar 61 being the bottom bar in the arrangement. These operating bars are mounted for movement in a longitudinal direction by an arrangement including a plurality of spaced-apart brackets 62 secured by screws 63 to the base plate 28, each operating bar being

independently movable. Each of the operating bars has a normal position and is movable toward the left into ten off-normal positions. The movements of the bars toward the left when they reach their tenth off-normal positions are arrested by a stop 62^a secured to the base plate 28 by screws 62^b.

The hundred bar 59 carries five lugs thereon respectively associated with the five elementary switches, the illustrated lugs 64 and 65 being respectively associated with the elementary switches 40 and 41. Each of the lugs is provided with an off-set finger which is adapted to engage a latch mounted on the carriage of the associated elementary switch. The lugs 64 and 65 are provided with off-set fingers 64^a and 65^a, respectively, which are adapted respectively to engage latches 66 and 67 pivotally mounted on the carriages 42 of the elementary switches 40 and 41, respectively. The latch 66 is pivotally mounted at 68 upon the carriage 42 of the elementary switch 40 and is biased by a spring, not shown, away from an associated slot 69 formed in a bar 70 rigidly secured by a strap 71 to the ten bar 60. When the finger 64^a on the lug 64 engages the latch 66, the latter is moved into the associated slot 69 in order to lock the carriage 42 of the elementary switch 40 to the bar 70 for movement in a longitudinal direction with the ten bar 60, thereby selecting the elementary switch 40 to be operated or rendering the elementary switch 40 operable to select a line from the first and second groups in the first division of lines in the conductor bank 24. The latch 67 is constructed in a similar manner, being adapted to be moved into an associated slot 72 formed in the bar 70, when the latch 67 is engaged by the finger 65^a on the lug 65. The lugs 64, etc., are successively spaced along the hundred bar 59 and arranged in such a manner that the fingers on the lugs successively engage the latches mounted on the carriages of the elementary switches as the hundred bar 59 is moved from its normal position, the fingers being arranged to engage the latch associated therewith when the hundred bar 59 occupies two adjacent off-normal positions. Thus, the finger 64^a engages the latch 66 when the hundred bar 59 is moved from its normal position into its first off-normal position, thereby locking the carriage 42 of the elementary switch 40 to the bar 70; and the finger 64^a remains in engagement with the latch 66 when the hundred bar 59 is moved into its second off-normal position. The latch 66 rides off of the end of the finger 64^a on the lug 64 carried by the hundred bar 59 when the hundred bar 59 is moved into its third off-normal position, thereby unlocking the carriage 42 of the elementary switch 40 from the bar 70. Thus, the carriage of the first elementary switch 40 is locked to the bar 70 when the hundred bar 59 occupies its first and second off-normal position; the carriage of the second elementary switch is locked to the bar 70 when the hundred bar 59 occupies its third and fourth off-normal position; etc. The arrangement of the lugs 64, etc., on the hundred bar 59 allows only one of the elementary switches to be rendered operable or to be selected for operation at any time; and any one of the elementary switches may be selected to be operated by moving the hundred bar to a corresponding off-normal position.

After the hundred bar 59 has been moved from its normal position into a predetermined off-normal position to cause a corresponding ele-

mentary switch to be selected and the carriage thereof to be locked to the bar 70, the ten bar 60 is moved from its normal position into a predetermined off-normal position, causing the carriage 42 of the selected elementary switch to be moved longitudinally toward the left from its normal position into a corresponding off-normal position, thereby to select corresponding levels or subgroups from the odd and even groups in the associated division of lines in the conductor bank 24. The carriage 42 of the selected elementary switch is moved with the ten bar 60 due to the engagement between the latch mounted on the carriage 42 of the selected elementary switch 15 and the associated slot formed in the bar 70 rigidly secured to the ten bar 60. The latch is retained in position in the associated slot during the movement of the ten bar 60 by a member individual to the selected elementary switch and having a guide edge associated with the latch. The illustrated members 72' and 73 are individual to the elementary switches 40 and 41, respectively, and have the guide edges 74 and 75 respectively associated with the latches 66 and 25 67, respectively. The members 72' and 73 are secured to a bar 76 by two sets of screws 77 and 78, respectively, the bar 76 being secured to the brackets 62. This arrangement positively insures that the carriage 42 of the selected elementary switch is locked to the bar 70 during the entire longitudinal movement of the bar 70 with the ten bar 60.

After the ten bar 60 has been moved from its normal position into a predetermined off-normal position, causing the carriage 42 of the selected elementary switch to be moved from its normal position into a corresponding off-normal position, thereby to select corresponding levels or subgroups from the odd and even groups in the 30 associated division of lines, the unit bar 61 is moved from its normal position into a predetermined off-normal position. This movement of the unit bar 61 causes the slide 43 mounted on the carriage 42 of the selected elementary switch 35 to be moved laterally from its normal position into a corresponding off-normal position, thereby to select corresponding lines from the previously selected levels or subgroups of lines. This movement of the slide 43 in response to the movement of the unit bar 61 is effected by an arrangement including an under-slide 79 and a bell crank 80 individual to the selected elementary switch, as is best shown in the operated elementary switch in Figs. 9 and 10. The under-slide 50 79 is mounted for movement in a lateral direction upon two substantially parallel laterally extending guide members secured to the base plate 28. One of these guide members comprises two aligned rods 81^a and 81^b, while the other guide member comprises an angle bar 82. The under-slide 79 is provided with two outwardly extending arms 83 and 84 embracing the guide rods 81^b and 81^a and an outwardly extending arm 85 engaging the guide bar 82 in order to guide the 55 lateral movement of the under-slide 79. Also, an upstanding flange 86 is provided on the rear edge of the under-slide 79 which slidably engages a downwardly projecting button 87 carried by the slide 43 of the selected elementary switch, 60 the button 87 having a slot therein which straddles the upper edge of the flange 86. This arrangement allows the carriage 42 and the slide 43 of the selected elementary switch to be moved longitudinally with respect to the under-slide 79 65 without any interference therewith.

The bell crank 80 is pivotally mounted at 88 upon a bracket 89 secured by screws 90 to the base plate 28. The bell crank 80 is provided with three outwardly extending arms 91, 92 and 93 and is biased in a clockwise direction by a coil 5 spring 94 extending between the outer end of the arm 91 and a fixture 95 carried by the base plate 28. The outer end of the arm 93 carries a roller 96 which engages an elongated slot 97 provided in the under-slide 79, the engagement between the roller 96 and the slot 97 constituting a driving engagement between the bell crank 80 and the under-slide 79. The outer end of the arm 92 engages an upstanding flange 98 provided on a fixture 99 secured to the unit bar 61 by a 15 screw 100.

A locking arrangement is provided in each elementary switch in order to control the movement of the slide 43 thereof. The locking arrangement individual to the elementary switch 41 comprises a locking plate 101 secured to a bar 102 by screws 103, the bar 102 being secured to the brackets 62. The locking plate 101 is provided with a downwardly extending flange 104 having ten notches 105 therein which correspond to the 20 ten off-normal positions of the carriage 42 and cooperate with an upstanding flange 106 provided on one side of the slide 43 adjacent the rear end thereof. More specifically, the rear end of the flange 106 engages the flange 104, when the carriage 42 of the elementary switch 41 occupies its 25 normal position, thereby to lock the slide 43 of the elementary switch 41 in its normal position against movement in a lateral direction. When the elementary switch 41 is selected to be operated and the carriage 42 thereof is moved longitudinally from its normal position into a predetermined off-normal position, the rear end of the flange 106 is moved into alignment with a 30 corresponding notch 105 in the flange 104, thereby to unlock the slide 43 for movement in a lateral direction, the slide 43 being restrained against movement in a lateral direction by the engagement between the flange 98 on the fixture 35 99 secured to the unit bar 61 and the outer end 40 of the arm 92 on the bell crank 80, at this time.

After the carriage 42 of the selected elementary switch 41 has been moved longitudinally into a predetermined off-normal position by the ten 50 bar 60, the unit bar 61 is moved longitudinally toward the left into a predetermined off-normal position. As the unit bar 61 is moved longitudinally, the flange 98 on the fixture 99 is moved away from the outer end of the arm 92 on the bell crank 80, causing the spring 94 to rotate the bell crank 80 in a clockwise direction about the pivot 88. It is noted that the flange 98 on the fixture 55 is sufficiently wide to prevent the outer end of the arm 92 on the bell crank 80 from disengaging the flange 98 as the bell crank 80 is rotated in a clockwise direction about the pivot 88. Rotation of the bell crank 80 in a clockwise direction causes the under-slide 79 to be moved laterally toward the rear of the switching unit through the 60 driving engagement between the roller 96 carried by the arm 93 on the bell crank 80 and the slot 97 in the under-slide 79. This movement of the under-slide 79 is transmitted to the slide 43 through the driving engagement between the flange 86 on the under-slide 79 and the button 87 carried by the slide 43. The lateral movement of the slide 43 is the same as that of the under-slide 79, which latter movement is proportional 65 to the rotational movement of the bell crank 80, 70 75

while the rotational movement of the bell crank 80 is proportional to the longitudinal movement of the unit bar 61. Thus, the movement of the slide 43 is proportional to the movement of the 5 unit bar 61, and when the unit bar 61 is moved from its normal position into a predetermined off-normal position, the slide 43 is moved from its normal position into a corresponding off-normal position.

10 From the above it will be understood that the slide 43 of only the selected elementary switch 41 will be moved laterally when the unit bar 61 is moved longitudinally, due to the fact that the rear or right-hand end of the flange 106 on the 15 slide 43 of only the selected elementary switch 41 will be aligned with a notch 105 in the flange 104 on the locking plate 101, as shown in Fig. 10. The rear ends of the flanges 106 on the slides 43 of the remainder of the elementary switches engage the flange 104 on the locking plates 101 associated therewith, thereby locking the slide 43 of the remainder of the elementary switches against lateral movement. When the slide 43 of the selected elementary switch 41 is moved into its 20 first off-normal position the flange 106 thereon enters the notch 105 in the flange 104 on the locking plate 101. This engagement between the flange 106 and the notch 105 in the flange 104 locks the carriage 42 of the selected elementary switch 41 against further movement in a longitudinal direction.

25 The rear edge of the carriage 42 of each elementary switch carries three insulating buttons 107, 108 and 109, respectively, arranged between the positive wipers 45 and 48, the negative wipers 46 and 49, and the control wipers 47 and 50, carried by the contact controlling member 44 mounted on the slide 43 thereof. These buttons cooperate with inwardly bent portions of the associated wipers in order to prevent vibration of and engagement between the respective positive, negative and control wipers of the first and second contact sets, when the slide 43 of the elementary switch occupies its normal position. 30 When the slide 43 of the selected elementary switch is moved from its normal position into its first off-normal position, the wipers of the first and second contact sets are moved respectively into engagement with the first lines of the adjacent levels or subgroups in the odd and even groups in the associated division of lines, and the inwardly bent portions of the wipers are moved out of engagement with the associated insulating buttons 107, 108 and 109. Also, each of the guide rods 81^a is provided with a stop 110 in order to arrest the movement of the under-slide 79, when the unit bar 61 is restored to its normal position. This stop 110 limits the lateral movement of the slide 43 of the elementary switch by engaging the arm 84 on the under-slide 79, and insures that the slide 43 will be arrested in its normal position.

35 In order to restore the operated elementary switch 41 to its idle position, the unit bar 61 is first moved toward the right back into its normal position. This movement of the unit bar 61 causes the bell crank 80 to be rotated in a counterclockwise direction about the pivot 88 against the bias of the spring 94, due to the driving engagement between the flange 98 on the fixture 99 secured to the unit bar 61 and the outer end of the arm 92 on the bell crank 80. This counterclockwise rotation of the bell crank 80 moves the under-slide 79 laterally toward the front of the switching unit through the driving engagement 40 between the roller 96 carried by the outer end of

the arm 93 on the bell crank 80 and the slot 97 in the under-slide 79. This movement of the under-slide 79 is transmitted to the slide 43 through the driving engagement between the flange 86 on the under-slide 79 and the button 87 5 carried by the slide 43, causing the slide 43 to be moved laterally toward the front or left-hand end of the switching unit, as shown in Fig. 10, back into its normal position. When the slide 43 is moved back into its normal position, the flange 106 thereon disengages the notch 105 in the flange 104 on the locking plate 101, thereby to unlock the carriage 42 of the elementary switch 41 for movement in a longitudinal direction back into its normal position. The ten bar 60 is then 15 moved toward the right back into its normal position, causing the carriage 42 to be moved toward the right back into its normal position through the driving engagement between the latch mounted on the carriage 42 and the associated 20 slot in the bar 70 rigidly secured to the ten bar 60. When the carriage 42 is moved back into its normal position, the rear end of the flange 106 on the slide 43 reengages the flange 104 on the locking plate 101, thereby to lock the slide 43 of the 25 elementary switch against movement toward the rear of the switching unit. Finally, the hundred bar 59 is moved toward the right back into its normal position, causing the finger 65^a on the lug 65 carried by the hundred bar 59 and associated 30 with the latch 67 mounted on the carriage 42 of the selected elementary switch 41 to disengage the latch, thereby allowing the spring biased latch to move out of the associated slot 72 in the bar 70, in order to unlock the selected elementary 35 switch from the bar 70 and to restore the same to its idle position. Thus, the switching unit is completely restored to its idle position at this time and may be reoperated as described above in order to select corresponding lines from sub-groups in the odd and even groups in any division of lines in the conductor bank 24.

40 In order to control the operating bars 59, 60 and 61 in the switching unit in the manner described above, an operating mechanism is provided which includes an escapement mechanism 111 and a reset mechanism 112, shown in Figs. 6, 7 and 11 to 16, inclusive. The escapement mechanism 111 includes three identical gears 113, 114 and 115 rotatably mounted on a fixed shaft 116, 50 one end of the shaft 116 being fixed to the base plate 28, and the other end thereof being fixed to a bracket 117 secured by screws 118 to the base plate 28. The gears 113, 114 and 115 are associated, respectively, in driving engagement with three racks 119, 120 and 121, which are respectively secured to the operating bars 59, 60 and 61, the rack 119 being secured to the hundred bar 59 by a rivet illustrated at 122. The racks 119, 120 and 121 are biased toward the left by three operating levers 123, 124 and 125 respectively secured thereto by pin and slot connections 126, 127 and 128, respectively. The levers 123, 124 and 125 are of identical construction, each being pivoted at one end to a pin 129 secured to the base plate 65 28 and being biased by a spring 130 individual thereto in a clockwise direction about the pivot pin 129. One end of each of the springs 130 is fixed to a pin 131 secured to the base plate 28 and the other end thereof is fixed to a corresponding 70 one of the levers 123, 124 and 125. The gears 113, 114 and 115 are restrained against movement in a counterclockwise direction by the associated driving racks 119, 120 and 121, respectively, by toothed escapement wheels 132, 133 and 134 re- 75

spectively secured thereto. The escapement wheels 132, 133 and 134 are provided with escapement members 135, 136 and 137, respectively, pivotally mounted on a pin 138 secured between 5 the bracket 117 and the base plate 28. The escapement members 135, 136 and 137 are of identical construction, and each comprises an escapement pawl and an outwardly extending operating arm. Each of the escapement members is 10 biased in a clockwise direction about the pivot pin 138 by a spring individual thereto, in order to bring the escapement pawl thereon into engagement with the associated escapement wheel. More specifically, the escapement member 135 15 comprises an escapement pawl 139 and an outwardly extending operating arm 140 and is biased by a spring 141 in a clockwise direction about the pivot pin 138, in order to bring the escapement pawl 139 into engagement with the associated escapement wheel 132. One end of each of the 20 springs individual to the escapement members 135, 136 and 137 is fixed to a pin 142 secured to the base plate 28, and the other end thereof is fixed to a corresponding one of the escapement 25 members.

The escapement mechanism 111 also includes an operating motor M1 of the electromagnetic type, comprising a winding 143 and a magnetic structure including a core 144, a frame 145 and an 30 armature 146. The armature 146 is pivotally mounted to the frame 145 by a pin 147 and is biased in a clockwise direction about the pivot pin 147 away from the core 144 into engagement with a stop 148 by a coil spring 149, one end of the 35 spring 149 being fixed to the armature 146 and the other end thereof being fixed to a pin 150 secured to the base plate 28. An arrangement including a plate 151 secured to the armature 146 by a screw 152 and provided with a striking flange 40 153 extending toward the operating arms of the escapement members 135, 136 and 137 is provided for operating the escapement members, thereby to rotate the escapement members in a counter-clockwise direction about the pivot pin 138 in 45 order to move the escapement pawl thereon out of engagement with the associated escapement wheels 132, 133 and 134. When one of the escapement members is thus rotated to move the escapement pawl thereon out of engagement with the 50 associated escapement wheel, the associated escapement wheel allows the gear secured thereto to be driven in a counterclockwise direction by the associated rack in driving engagement therewith, thereby to move the associated operating bar longitudinally toward the left.

An arrangement including a mechanism 154 is provided in order to control the escapement mechanism 111. This escapement control mechanism 154 comprises a ratchet wheel 155 rotatively 55 mounted upon a fixed pin 156 secured to the base plate 28, and three substantially disc-shaped cam members 157, 158 and 159 rigidly secured to the ratchet wheel 155, as best shown in Figs. 7, 14 and 15. The periphery of each of the cam members is 60 provided with a plurality of projections which are spaced apart by intervening depressions. More specifically, the cam member 157 is provided with four projections 157^a which are spaced apart by intervening depressions 157^b. In a similar manner, the cam members 158 and 159, respectively, are provided with four projections 158^a and 159^a, which are respectively spaced apart by intervening 65 depressions 158^b and 159^b. Three bell cranks 160, 161 and 162 are respectively associated with 70 the cam members 157, 158 and 159, these bell 75

cranks being pivotally mounted on a pin 163 extending between the bracket 117 and the base plate 28. Each of the bell cranks is provided with two outwardly extending arms, the extreme outer end of one of the arms having a finger adapted to ride upon the periphery of the associated cam member. More specifically, the bell crank 160 is provided with two outwardly extending arms 160^a and 160^b, the extreme outer end of the arm 160^a having a finger 160^c adapted to ride upon the 10 periphery of the associated cam member 157. In a similar manner, the bell cranks 161 and 162 are respectively provided with two outwardly extending arms 161^a, 161^b and 162^a, 162^b, the extreme outer ends of the arms 161^a and 162^a being respectively provided with fingers 161^c and 162^c adapted respectively to ride upon the peripheries of the cam members 158 and 159. Three tappets 164, 165 and 166 are respectively pivotally secured by rivets 167, 168 and 169, respectively, to the arms 20 160^b, 161^b and 162^b, respectively, of the bell cranks 160, 161 and 162 respectively. Each of the tappets is provided with a head to which one end of a coil spring individual thereto is fixed, the other end of the spring being fixed to a pin 170 secured to 25 the base plate 28. More specifically, the tappet 164 is provided with a head 164^a to which one end of the coil spring 171 individual thereto is fixed, the other end of the spring 171 being fixed to the pin 170. In a similar manner, the tappets 165 and 166 are provided, respectively, with heads 165^a and 166^a to which the coil springs 172 and 173 individual to the tappets 165 and 166, respectively, are secured, the other ends of the springs 172 and 173 being secured to the pin 170. The tappets 164, 30 165 and 166 are arranged between the operating arms of the escapement members 135, 136 and 137 and the striking flange 153 provided on the plate 151 secured to the armature 146. Normally, the springs 171, 172 and 173 bias the heads 164^a, 40 165^a and 166^a, respectively, of the tappets 164, 165 and 166, respectively, toward the front of the switching unit out of positions of engagement with the striking flange 153. The biases of the springs 171, 172 and 173 cause the bell cranks 160, 161 45 and 162, respectively, to be rotated in a clockwise direction about the pivot pin 163, thereby bringing the fingers 160^c, 161^c, and 162^c, respectively, into engagement with the peripheries of the cam members 157, 158 and 159, respectively. 50

The escapement control mechanism 154 is so constructed and arranged that when the finger on the extreme outer end of one of the arms of the bell crank engages one of the depressions in the periphery of the associated cam member, the bell 55 crank is rotated in a clockwise direction about the pivot pin 163 by the coil spring extending between the pin 170 and the head of the tappet pivotally mounted on the other arm of the bell crank, thereby causing the head of the tappet to be 60 moved out of striking position with respect to the striking flange 153 on the plate 151 carried by the armature 146. On the other hand, when the finger on the extreme outer end of one of the arms of a bell crank engages one of the projections on 65 the periphery of the associated cam member, the bell crank is rotated in a counterclockwise direction about the pivot pin 163 against the bias of the coil spring extending between the pin 170 and the head of the tappet pivotally mounted on the other arm of the bell crank, thereby causing the head of the tappet to be moved into striking position 70 with respect to the striking flange 153 on the plate 151 secured to the armature 146. The movements 75 of the tappets into their striking positions are 75

guided and limited by a guide and stop 170^a carried by the base plate 28.

More specifically, when the finger 160^c on the extreme outer end of the arm 160^a of the bell crank 160 engages one of the depressions 157^b in the periphery of the associated cam member 157, the bell crank 160 is rotated in a clockwise direction about the pivot pin 163 by the coil spring 171 extending between the pin 170 and the head 164^a of the tappet 164 pivotally mounted by the rivet 167 on the arm 160^b of the bell crank 160, thereby causing the head 164^a of the tappet 164 to be moved out of striking position with respect to the striking flange 153 on the plate 151 carried by the armature 146. On the other hand, when the finger 160^c on the extreme outer end of the arm 160^a of the bell crank 160 engages one of the projections 157^a on the periphery of the associated cam member 157, the bell crank 160 is rotated in a counterclockwise direction about the pivot pin 163 against the bias of the coil spring 171 extending between the pin 170 and the head 164^a of the tappet 164 pivotally mounted by the rivet 167 on the arm 160^b of the bell crank 160, thereby causing the head 164^a of the tappet 164 to be moved into striking position with respect to the striking flange 153 on the plate 151 carried by the armature 146. The construction and arrangement of each of the bell cranks 161 and 162 associated with the cam members 158 and 159, respectively, is the same as that of the bell crank 160 described above.

When the head of any one of the tappets is moved into striking position with respect to the striking flange 153 on the plate 151 carried by the armature 146, the associated escapement member pivotally mounted on the pin 138 is conditioned to be operated to allow the associated escapement wheel to be rotated in a counterclockwise direction by the associated rack in driving relation with the gear secured thereto. More specifically, when the head 164^a of the tappet 164 is moved into striking position with respect to the striking flange 153, the associated escapement member 135 pivotally mounted on the pin 138 is conditioned to be operated to allow the associated escapement wheel 132 to be rotated in a counterclockwise direction by the associated rack 119 in driving relation with the gear 113 secured thereto.

At this time, when the operation motor M1 is energized, the armature 146 thereof is moved in a counterclockwise direction about the pivot pin 147 against the bias of the coil spring 149, causing the striking flange 153 on the plate 151 carried by the armature 146 to engage the head 164^a of the tappet 164. The head 164^a of the tappet 164 is then moved into engagement with the arm 140 on the escapement member 135, thereby to cause the escapement member 135 to be rotated in a counterclockwise direction about the pivot pin 138 against the bias of the coil spring 141. When the escapement member 135 is rotated in a counterclockwise direction, the escapement pawl 139 is moved out of engagement with the escapement wheel 132, thereby allowing the rack 119 in driving engagement with the gear 113 secured to the escapement wheel 132 to move the escapement wheel 132 one step in a counterclockwise direction, further movement of the escapement wheel in a counterclockwise direction being arrested by the inwardly curved finger 140^a provided on the operating arm 140. The finger 140^a on the operating arm 140 serves as a detent to prevent further counterclockwise rotation of the escapement wheel 132. The rotation of the

escapement wheel 132 one step in a counterclockwise direction allows the rack 119 to be moved longitudinally one step toward the left by the lever 123 mounted on the pivot pin 129 and pivotally secured by the pin and slot connection 126 to the rack 119, this movement of the rack 119 being produced by rotation of the lever 123 in a clockwise direction about the pivot pin 129 under the influence of the coil spring 130. This movement of the rack 119 is transmitted to the hundred bar 59 connected to the rack 119, causing the hundred bar to be moved longitudinally one step from its normal position into its first off-normal position, thereby to cause the first elementary switch 40 to be selected to be operated as previously explained. When the operating motor M1 is deenergized, the armature 146 thereof is rotated in a clockwise direction about the pivot pin 147 by the coil spring 149, causing the head 164^a of the tappet 164 to disengage the operating arm 140 of the escapement member 135, thereby allowing the escapement member 135 to be rotated in a clockwise direction about the pivot pin 138 by the coil spring 141. When the escapement member 135 is rotated in a clockwise direction, the detent 140^a disengages the escapement wheel 132 shortly after the escapement pawl 139 on the escapement member 135 engages the escapement wheel 132, the escapement pawl 139 retaining the escapement wheel against further counterclockwise movement, at this time. Upon each subsequent energization of the operating motor M1, the escapement wheel 132 is rotated a corresponding step in a counterclockwise direction as described above. Thus, the hundred bar 59 is moved longitudinally toward the left step by step a predetermined number of steps corresponding to the number of times the operating motor M1 is repeatedly energized, thereby causing a corresponding one of the elementary switches to be selected to be operated, as previously explained.

The striking flange 153 on the plate 151 carried by the armature 146 is sufficiently long to engage the head of any one of the tappets 164, 165 and 166, which occupies a striking position. Thus, it will be apparent that the hundred bar 59, the ten bar 60 and the unit bar 61 may be selectively operated by selectively moving the heads of the tappets 164, 165 and 166 into striking positions, the number of steps which any one of the operating bars is moved longitudinally toward the left being dependent upon the number of times the operating motor M1 is repeatedly energized while the head of the corresponding tappet occupies a striking position. From the foregoing it is apparent that the operating bars 59, 60 and 61 may be selectively moved from their normal positions into any one of their off-normal positions by selectively controlling the movements of the tappets 164, 165 and 166, and by selectively controlling the number of times the operating motor M1 is repeatedly energized when the tappets occupy striking positions.

The escapement control mechanism 154 also includes an operating motor M2 of the electromagnetic type, comprising a winding 174 and a magnetic structure including a core 175, a frame 176 and an armature 177. The armature 177 is pivotally mounted to the frame 176 by a pin 178 and is provided with an outwardly extending arm 179 which is biased by a coil spring 180 into engagement with a stop 181. One end of the coil spring 180 is fixed to the arm 179 and the other end thereof is fixed to a pin 182 se-

cured to the base plate 28, while the stop 181 is carried by a bracket 183 secured by screws 184 to the base plate 28. A pawl 185 is pivotally mounted by a pin 186 to the extreme outer end of the arm 179 and is biased in a clockwise direction about the pivot pin 186 by a coil spring 187 extending between the pawl 185 and the arm 179. The pawl 185 is biased by the spring 187 into engagement with the associated ratchet wheel 155 and the movement thereof is guided by a guide bracket 188 secured by a screw 189 to the base plate 28. Also, a detent 190 pivotally mounted on a pin 191 secured to the base plate 28 is provided in order to retain the ratchet wheel 155 in any one of its operated positions, the detent 190 being biased by a spring 191 into engagement with a stop 192 secured to the base plate 28. When the winding 174 of the operating motor M2 is energized, the armature 177 is moved in a counterclockwise direction about the pivot pin 178, causing the pawl 185 carried by the arm 179 to be moved away from the associated ratchet wheel 155 against the bias of the spring 180. When the winding 174 of the operating motor M2 is then deenergized, the armature 177 is rotated in a clockwise direction about the pivot pin 178 by the spring 180, causing the arm 179 to be moved into engagement with the stop 181, thereby to cause the pawl 185 to engage the ratchet wheel 155. The engagement of the pawl 185 and the associated ratchet wheel 155 causes the ratchet wheel 155 to be rotated one step in a clockwise direction, the ratchet wheel being retained in this operating position by the detent 190. Each time the winding 174 of the operating motor M2 is energized and then deenergized, the ratchet wheel 155 is rotated one step in a clockwise direction as explained above.

The four projections on each of the cam members 157, 158, 159 are equally spaced apart a distance equal to five steps of the ratchet wheel 155 to which each of the cam members is secured, and the cam members are so arranged with respect to each other that the projections on the peripheries thereof are disposed in staggered relation in a manner more particularly described below. When the switching unit occupies an idle position, the ratchet wheel occupies a normal position wherein the fingers 160^c, 161^c and 162^c engage depressions 157^b, 158^b and 159^b in the peripheries of the cam members 157, 158 and 159, respectively, thereby causing the heads of the tappets 164, 165 and 166 to occupy their non-striking positions, as previously explained. When the switching unit is operated, the ratchet wheel 155 is first rotated one step in a clockwise direction into a first off-normal position wherein the finger 160^c engages a projection 157^a on the periphery of the cam member 157 and the fingers 161^c and 162^c respectively engage depressions 158^b and 159^b formed in the peripheries of the cam members 158 and 159, respectively, thereby causing the head of the tappet 164 to be moved into its striking position and the heads of the tappets 165 and 166 to be retained in their non-striking positions. The ratchet wheel 155 is then rotated into a second off-normal position wherein the finger 161^c engages a projection 158^a on the periphery of the cam member 158 and the fingers 160^c and 162^c respectively engage depressions 157^b and 159^b formed in the peripheries of the cam members 157 and 159, respectively, thereby causing the head of the tappet 165 to be moved into its striking position and the heads of the tappets

164 and 166 to occupy their non-striking positions. The ratchet wheel 155 is then rotated into a third off-normal position wherein the finger 162^c engages a projection 159^a on the periphery of the cam member 159 and the fingers 160^c and 161^c respectively engage depressions 157^b and 158^b formed in the peripheries of the cam members 157 and 158, respectively, thereby causing the head of the tappet 166 to be moved into its striking position and the heads of the tappets 164 and 165 to occupy their non-striking positions. The ratchet wheel 155 is then rotated into a fourth off-normal position wherein the fingers 160^c, 161^c and 162^c engage depressions 157^b, 158^b and 159^b in the peripheries of the cam members 157, 158 and 159, respectively, thereby causing the heads of the tappets 164, 165 and 166 to occupy their non-striking positions. When the operated switching unit is restored to its idle position, the ratchet wheel 155 is rotated into a fifth off-normal position wherein the fingers 160^c, 161^c and 162^c engage depressions 157^b, 158^b and 159^b in the peripheries of the cam members 157, 158 and 159, respectively, as explained in connection with the positions of the fingers when the ratchet wheel 155 occupies its normal position, the fifth off-normal position of the ratchet wheel 155 constituting a normal position thereof for the next cycle of operation of the switching unit.

The reset mechanism 112 comprises an operating motor M3 including a magnetic structure having two core legs 193 and 194 displaced substantially 90° with respect to each other and provided with energizing windings 195 and 196, respectively. The operating motor M3 also includes a frame 197 secured by a number of screws 198 to the base plate 28, and a bracket 199 secured by a number of screws 200 to the frame 197. A rotor 201 is disposed between the core legs 193 and 194 and is rotatably mounted between the frame 197 and the bracket 199. The rotor 201 includes two diametrically disposed pole pieces 202, each provided with an elongated leading pole tip 202^a. A commutator arrangement is provided for the operating motor M3, which includes a substantially disc-shaped insulating cam 203 mounted on the rotor 201 and two contact sets 204 and 205, in order to control the energization of the windings 195 and 196. The contact set 204 includes two cooperating resilient contact springs 206 and 207 biased into engagement and movable into disengagement, and the contact set 205 includes two cooperating resilient contact springs 208 and 209 biased into engagement and movable into disengagement. The contact springs 207 and 209 of the contact sets 204 and 205, respectively, are extended into engagement with the periphery of the insulating cam 203, these contact springs being adapted to ride upon the periphery of the insulating cam. The periphery of the cam 203 is provided with two diametrically disposed projections 203^a having gradually inclined surfaces therebetween, the arrangement being such that the contact springs of the contact sets 204 and 205 are alternately engaged. The windings 195 and 196 are energized in parallel circuit relation from a suitable source of direct current supply. The contact set 204 is included in series circuit relation with the winding 196, and the contact set 205 is included in series circuit relation with the winding 195.

This commutator arrangement causes the contact springs of the contact set 204 to be disengaged and the contact springs of the contact

set 205 to be engaged, when the leading edge of the pole tip 202^a on one of the pole pieces 202 occupies a position adjacent the leading tip of the core leg 193, thereby to cause the winding 195 to be energized and the winding 196 to be deenergized. Also, this commutator arrangement causes the contact springs of the contact set 204 to be engaged and the contact springs of the contact set 205 to be disengaged, when the leading edge of the pole tip 202^a on one of the pole pieces 202 occupies a position adjacent the leading tip of the core leg 194, thereby to cause the winding 196 to be energized and the winding 195 to be deenergized. The alternate energization of the windings 195 and 196 causes the rotor 201 to be rotated in a clockwise direction in a well known manner.

The rotor 201 of the operating motor M3 is arranged in driving relation with a reset cam member 210 rigidly secured to a pin 211 rotatably supported by the base plate 28. The reset cam member 210 is driven by the rotor 201 through a gear train including a pinion 212 rigidly secured to the shaft of the rotor 201. The pinion 212 is arranged in driving relation with a gear 213 rotatably supported on a pin 214 and secured to the base plate 28. The gear 213 is rigidly secured to a pinion 215 arranged in driving relation with a gear 216 rigidly secured to a pin 217 rotatably supported by the base plate 28. Also, a pinion 218 is rigidly secured to the pin 217 and arranged in driving engagement with a gear 219 rigidly secured to the pin 211. The cam member 210 carries a roller 220 and the gear 219 carries a roller 221, the roller 220 being associated with two reset fingers 123^a and 124^a provided on the operating levers 123 and 124, respectively, and the roller 221 being associated with a reset finger 125^a provided on the operating lever 125. The roller 220 is adapted to engage the ends of the fingers 123^a and 124^a when the cam 211 is rotated in a counterclockwise direction by the operating motor M3, in order to cause the levers 123 and 124 respectively to be rotated in a counterclockwise direction about the pivot pin 129, thereby to cause the hundred bar 59 and the ten bar 60 to be moved longitudinally toward the right from their predetermined off-normal positions back into their normal positions. In a similar manner, the roller 221 is adapted to engage the end of the finger 125^a when the gear 219 is rotated in a counterclockwise direction by the operating motor M3, in order to cause the lever 125 to be rotated in a counterclockwise direction about the pivot pin 129, thereby to cause the unit bar 61 to be moved longitudinally toward the right from its predetermined off-normal position back into its normal position. The rollers 220 and 221 are disposed angularly with respect to each other in such a manner that the roller 221 is brought into engagement with the finger 125^a before the roller 220 is brought into engagement with the fingers 123^a and 124^a, thereby causing the unit bar 61 to be moved back into its normal position prior to the movement of the ten bar 60 and the hundred bar 59 back into their normal positions.

From the above, it will be understood that the pin 211 to which the cam member 210 and the gear 219 are secured must be rotated one revolution in a counterclockwise direction in order to release the switching unit and return the same to its idle position. In order to insure that the pin 211 is rotated exactly one revolution when the operating motor M3 is energized, an arrangement is provided which includes a contact set 222

supported by the bracket 198. The contact set 222 includes a pair of cooperating flexible contact springs 223 and 224 normally biased into disengagement and adapted to be moved into engagement by the cam member 210, the contact spring 224 being provided with an extended portion adapted to ride upon the periphery of the cam member 210. The contact set 222 is included in a secondary energizing circuit for the operating motor M3. In releasing the switch unit, the operating motor M3 is first energized by way of a primary energizing circuit independent of the contact set 222, and after a predetermined rotation of the cam member 210, the contact springs of the contact set 222 are engaged. Shortly thereafter, the primary energizing circuit of the operating motor M3 is interrupted, the operating motor being energized only by way of the secondary energizing circuit. After the cam member 210 has been rotated one revolution, the projecting end of the contact spring 224 rides into a depression 210^a provided in the periphery of the cam member 210, causing the contact springs of the contact set 222 to be disengaged, thereby to interrupt the secondary energizing circuit of the operating motor M3 and to arrest operation thereof.

An arrangement is provided for indicating the idle or particular operated position of the switching unit which comprises three levers 225, 226 and 227 pivotally mounted intermediate their ends upon a pin 228 provided on a standard 229 secured by screws 230^a to the base plate 28. One end of each of the levers carries a flag bearing indicia and the other end thereof is pivotally secured to a corresponding one of the racks 119, 120 and 121. More specifically, one end of the levers 225, 226 and 227 carries a flag 230, 231 and 232, respectively, and the other end thereof is secured to the racks 119, 120 and 121 by the pin 40 and slot connections 126, 127 and 128, respectively. Each of the flags is associated with the aperture 33 provided in the escutcheon plate 34 secured to the flange 29 extending along the front edge of the switching unit. The indicia provided on each flag comprises one letter and ten numerals arranged in spaced relation thereon, which are adapted to be moved individually into alignment with the aperture 33 in the escutcheon plate 34, and which correspond to the normal and the ten off-normal positions of the associated operating bar. When the switching unit occupies an idle position, the operating bars 59, 60 and 61 occupy their normal positions and the letter "N" is visible through the aperture 33 in the escutcheon plate 34 on each of the flanges 230, 231 and 232. On the other hand, when the switching unit is operated to any predetermined operating position, the corresponding numerals on the flags 230, 231 and 232 are visible through the aperture 33 in the escutcheon plate 34 to indicate the particular operated position of the switching unit.

The switching unit is provided with suitable arrangements adapted to be utilized in indicating and controlling certain operations thereof, in a manner more fully described subsequently. More specifically, the switching unit is provided with a pair of contact sets 233 and 230 mounted on a bracket 234 secured by screws 234^a to the base plate 28. The contact set 233 comprises a pair of cooperating flexible contact springs 235 and 236 biased into engagement and adapted to be moved into disengagement by an insulating button 146^a carried by the armature 146 of the operating motor M1, the button 146^a being adapted 75

to engage an extended portion of the contact spring 236. The contact springs of the contact set 233 are moved into disengagement each time the winding 143 of the operating motor M1 is energized. The contact set 233 is included in a control circuit more fully described subsequently.

The contact set 280 comprises a pair of cooperating flexible contact springs 281 and 282 biased into engagement and adapted to be moved into disengagement by an insulating button 179^a carried by the arm 179 of the operating motor M2, the button 179^a being adapted to engage an extended portion of the contact spring 282. The contact springs of the contact set 280 are moved into disengagement each time the winding 174 of the operating motor M2 is energized. The contact set 280 is also included in a control circuit subsequently described.

A set of contact springs 237 is mounted on a bracket 238 secured by screws 238^a to the base plate 28 and associated with the rack 119 secured to the hundred bar 59. The contact set 237 comprises a pair of outside contact springs 239 and 240 and an intermediate contact spring 241, these contact springs being normally in disengagement. The intermediate contact spring 241 carries a roller 242 on the outer end thereof which cooperates with an insulating cam plate 243 secured to the rack 119. The cam plate 243 is provided with an intermediate portion 243^a, five projections 243^b extending outwardly from the intermediate portion and five depressions 243^c extending inwardly from the intermediate portion. The intermediate portion 243^a provided on the cam plate 243 corresponds to the normal position of the rack 119; the five projections 243^b provided on the cam plate 243 correspond to the five odd off-normal positions of the rack 119; while the five depressions 243^c provided in the cam plate 243 correspond to the five even off-normal positions of the rack 119. When the roller 242 carried on the outer end of the intermediate spring 241 engages the intermediate portion 243^a of the cam plate 243, the intermediate contact spring 241 disengages the outside contact springs 239 and 240. On the other hand, when the roller 242 engages one of the projections 243^b on the cam plate 243, the intermediate contact spring 241 is moved into engagement with the outside contact spring 240; and when the roller 242 engages one of the depressions 243^c provided in the cam plate 243, the intermediate contact spring 241 is moved into engagement with the outside contact spring 239. Thus, when the rack 119 occupies its normal position, the contact springs of the contact set 237 are disengaged; when the rack 119 occupies any odd off-normal position, the contact springs 241 and 240 are engaged; and when the rack 119 occupies any even off-normal position, the contact springs 241 and 239 are engaged. The contact set 237 is included in a circuit which is controlled in accordance with the odd or even operated position of the rack 119 and the hundred bar 59 secured thereto, for a purpose subsequently described.

A contact set 245 is associated with the hundred bar 59 and the ten bar 60. The contact set 245 comprises two pairs of contact springs 247, 248 and 251, 252, respectively, the contact springs 247, 248 and 251, 252 being provided with extended options 249 and 253 respectively associated with the cam plate 243 carried by the rack 119, and a similar cam plate carried by the rack 120, the rack 120 being secured to the ten bar 60. Normally, the

contact springs 247, 248 and 251, 252 are biased into engagement and are moved into disengagement by the cam plates carried by the racks 119 and 120. These contact springs are so constructed and arranged that when either one of the racks 119 or 120 is moved into an off-normal position, both pairs of the contact springs of the contact set 245 are moved into engagement. The contact springs 247, 248 and 251, 252 of the contact set 245 are included in a circuit which is controlled in accordance with the normal and off-normal positions of the racks 119 and 120 and the hundred bar 59 and the ten bar 60, respectively secured thereto for a subsequently described purpose.

Also, a jack 254 mounted on a bracket 255, secured to the base plate 28 by the screws 255^a, is provided, which is disposed in alignment with the opening 35 formed in the flange 29 extending along the front edge of the switching unit. The jack 254 is adapted to receive a plug inserted through the opening 35 formed in the flange 29, and is wired in a suitable testing circuit in order to provide an arrangement for testing any desired electrical condition of the switching unit.

The escapement control mechanism 154 also constitutes a sequence switch, two contact sets 260 and 270 being associated therewith. The contact set 260 comprises a pair of cooperating contact springs 261 and 262 biased into engagement, the contact spring 262 being provided with an extended portion 263 adapted to ride upon the periphery of a disc-shaped cam member 264. The cam member 264 is secured to the cam members 157, 158 and 159, and is rotatable therewith about the pin 156. Four equally spaced-apart depressions 264^a are provided in the periphery of the cam member 264 which correspond to the fourth off-normal positions of the ratchet wheel 155. When the ratchet wheel 155 of the escapement control mechanism 154 occupies its fourth off-normal position, the extended portion 263 provided on the contact spring 262 rides into one of the depressions 264^a in the periphery of the cam member 264, causing the contact springs 261 and 262 of the contact set 260 to be moved into engagement. The contact set 260 is included in a circuit which is controlled by the movement of the escapement control mechanism 154 into its fourth off-normal position. The contact set 270 comprises a pair of cooperating contact springs 271 and 272 biased into disengagement, the contact spring 272 being provided with an extended portion 273 adapted to ride upon the periphery of a disc-shaped cam member 274. The cam member 274 is secured to the cam members 157, 158 and 159 and is rotatable therewith about the pin 156. Four equally spaced-apart depressions 274^a are provided in the periphery of the cam member 274 which correspond to the normal or fifth off-normal positions of the ratchet wheel 155. When the ratchet wheel 155 of the escapement control mechanism 154 occupies its normal or fifth off-normal position, the extended portion 273 provided on the contact spring 272 rides into one of the depressions 274^a in the periphery of the cam member 274, causing the contact springs 271 and 272 of the contact set 270 to be moved into disengagement. The contact set 270 is included in a circuit which is controlled by the movement of the escapement control mechanism 154 into its normal or fifth off-normal position.

Referring now to the operation of the switching unit described and assuming that the switch-

ing unit is to be operated to select a particular line from the conductor bank 24, such, for example, as the fourth line in the third level or subgroup in the second group in the first division 5 of lines in the conductor bank 24, the switching unit is controlled by an impulse transmitter connected and arranged in a control circuit including the operating motors M1, M2 and M3, in a manner more fully described subsequently. In 10 order to cause the switching unit to operate and select the line noted above; a single energizing impulse is first transmitted to the operating motor M2, thereby to cause the ratchet wheel 155 of the escapement control mechanism 154 to be rotated from its normal position into its 15 first off-normal position. When the ratchet wheel 155 is rotated into its first off-normal position, the head 164^a of the tappet 164 is moved into its striking position as previously 20 explained, thereby conditioning the escapement wheel 132 in the escapement mechanism 111 to be rotated step by step in a counterclockwise direction in response to the successive energizations 25 of the operating motor M1.

25 The impulsing device is then operated to transmit a first series of impulses, comprising two impulses, thereby to cause the operating motor M1 to be energized two times successively. The two successive energizations of the operating motor 30 M1 allow the escapement wheel 132 to be rotated two steps in a counterclockwise direction, thereby to cause the hundred bar 59 to be moved longitudinally toward the left from its normal position into its second off-normal position, as 35 previously described. This movement of the hundred bar 59 causes the finger 64^a on the lug 64 carried by the hundred bar 59 to engage the latch 66 mounted on the carriage 42 of the elementary switch 40 and to move the latch 66 40 into the associated slot 69 provided in the bar 70 rigidly secured by the strap 71 to the ten bar 60, as previously explained. This operation of the hundred bar 59 selects the elementary switch 40 to be operated, in order to select correspond- 45 ing lines from the first and second groups in the associated first division of lines. At the end of the first series of impulses, a single energization impulse is transmitted to the operating motor M2, thereby to cause the ratchet wheel 155 of the escapement control mechanism 154 to be rotated into its second off-normal position. When the ratchet wheel 155 is rotated into its 50 second off-normal position, the head 165^a of the tappet 165 is moved into its striking position, thereby conditioning the escapement wheel 133 in the escapement mechanism 111 to be rotated step by step in a counterclockwise direction in response to successive energizations of the operating motor M1.

55 The impulsing device is then operated to transmit a second series of impulses, comprising three impulses, thereby to cause the operating motor M1 to be energized three times successively. The three successive energizations of the operating motor M1 allow the escapement wheel 133 to be rotated three steps in a counterclockwise direction, thereby to cause the ten bar 60 to be moved longitudinally toward the left from its normal position into its third off-normal position. This movement of the ten bar 60 causes the carriage 42 of the selected elementary switch 40 to be moved longitudinally toward the left from its normal position into its third off-normal position, due to the engagement between the latch 66 and the slot 69 formed in the bar 70, which

bar is rigidly secured by the strap 71 to the ten bar 60, as previously explained. This movement of the carriage 42 of the selected elementary switch 40 causes the elementary switch 40 to select the third level or subgroup in the first and second groups in the associated first division. At the end of the second series of impulses, a single energizing impulse is transmitted to the operating motor M2, thereby to cause the ratchet wheel 155 of the escapement control mechanism 154 to be rotated into its third off-normal position. When the ratchet wheel 155 is rotated into its third off-normal position, the head 166^a of the tappet 166 is moved into its striking position, thereby conditioning the escapement wheel 134 in the escapement mechanism 111 to be rotated step by step in a counterclockwise direction in response to the successive energizations of the operating motor M1.

55 The impulsing device is then operated to transmit a third series of impulses, comprising four impulses, thereby to cause the operating motor M1 to be energized four times successively. The four successive energizations of the operating motor M1 allow the escapement wheel 134 to be rotated four steps in a counterclockwise direction, thereby to cause the unit bar 61 to be moved longitudinally toward the left from its normal position into its fourth off-normal position. This movement of the unit bar 61 allows the bell crank 80 in the selected elementary switch 40 to be rotated four steps in a clockwise direction about the pivot pin 88 by the coil spring 94, as previously explained. This rotation of the bell crank 80 is transmitted to the under-slide 79 through the engagement between the roller 96 carried by the arm 93 of the bell crank 80 and the slot 97 in the under-slide 79, thereby to cause the under-slide 79 to be moved laterally toward the rear of the switching unit. This movement of the under-slide 79 is transmitted to the slide 43 of the selected elementary switch 40 due to the engagement between the flange 86 on the under-slide 79 and the button 87 carried by the slide 43, thereby to cause the slide 43 to be moved laterally toward the rear of the switching unit from its normal position into its fourth off-normal position. When the slide 43 of the selected elementary switch 40 is moved into its fourth off-normal position, the fourth lines in the third levels or subgroups in the first and second groups in the associated first division are selected. The wipers 45, 46 and 47 of the first contact set in the elementary switch 40 engage the positive, negative and control conductors, respectively, of the selected line in the first group; and the wipers 48, 49 and 50 of the second contact set in the elementary switch 40 engage the positive, negative and control conductors, respectively, of the selected line in the second group.

60 Thus, the elementary switch 40 is operated simultaneously to select the fourth lines in the third levels or subgroups in the first and second groups in the associated first division of lines in the conductor bank 24 when the series of impulses corresponding to the digits 2-3-4 are successively transmitted thereto. From the foregoing description of the operation of the switching unit, it is apparent that these same lines will be selected when the series of impulses corresponding to the digits 1-3-4 are successively transmitted thereto, in view of the fact that the elementary switch 40 is selected to be operated when the first series of impulses transmitted cor- 75

responds to either the digit 1 or 2. While corresponding lines are selected by the elementary switch 40, when either the digits 1-3-4 or 2-3-4 are dialed successively in the order named, electrical connections to these lines may be selectively established depending upon whether the first series of impulses transmitted corresponds to the digit 1 or 2, in view of the fact that the contact set 237 associated with the cam 10 plate 243 secured to the rack 119, to which the hundred bar 59 is secured, is operated to register the odd or even off-normal position of the hundred bar 59. Means is included in the circuit comprising the contact set 237, which is controlled in such a manner that electrical connections are selectively extended to the first and second contact sets mounted on the contact controlling member 44 carried by the slide 43 of the elementary switch 40 depending upon whether 20 the first series of impulses transmitted corresponds to an odd or even digit, as is more fully described subsequently.

At the end of the third series of impulses, a single energizing impulse is transmitted to the 25 operating motor M2, thereby to cause the ratchet wheel 155 of the escapement control mechanism 154 to be rotated into its fourth off-normal position. When the ratchet wheel 155 is rotated into its fourth off-normal position, the head of each 30 of the tappets 164, 165 and 166 occupies its non-striking position, as previously described.

In order to interrupt the established connection to the fourth line in the third level or subgroup in the first or second group in the first 35 division in the conductor bank 24 and to restore the switching unit to its idle position, a single energizing impulse is transmitted to the operating motor M2 of the escapement control mechanism 154, and the operating motor M3 of the reset mechanism 112 is energized. The single energizing 40 impulse transmitted to the operating motor M2 causes the ratchet wheel 155 to be rotated into its fifth off-normal position, which off-normal position of the ratchet wheel 155 constitutes a normal position thereof, thereby to condition the 45 escapement control mechanism 154 to be responsive to a further single energizing impulse in order to initiate another operation of the switching unit, after the switching unit has been restored to its idle position. The energization of the operating motor M3 of the reset mechanism 112 causes the pin 211 to be rotated one revolution in a counterclockwise direction, as previously explained. As the pin 211 is rotated in a 50 counterclockwise direction, the roller 221 first engages the finger 125^a on the lever 125, causing the lever 125 to move the unit bar 61 from its fourth off-normal position back into its normal position. This movement of the unit bar 61 rotates the bell crank 80 in the elementary switch 60 40 in a counterclockwise direction about the pivot pin 88 against the bias of the coil spring 94, due to the engagement between the flange 98 on the fixture 99 secured to the unit bar 61 and the arm 92 on the bell crank 80. This rotation of the bell 65 crank 80 is transmitted to the under-slide 79 due to the engagement between the roller 96 carried by the arm 93 of the bell crank 80 and the slot 97 in the under-slide 79, causing the under-slide 79 to be moved laterally toward the front of the 70 switching unit. This movement of the under-slide 79 is transmitted to the slide 43 of the elementary switch 40, due to the engagement between the flange 86 on the under-slide 79 and the button 87 carried by the slide 43, thereby to 75 cause the contact sets carried by the slide 43 of

the elementary switch 40 to disengage the fourth conductors in the third levels or subgroups in the first and second groups in the associated first division. Subsequently, the roller 220 engages the fingers 123^a and 124^a on the levers 123 and 124, respectively. When the finger 124^a on the lever 124 is engaged, the ten bar 60 is moved longitudinally toward the right from its third off-normal position back into its normal position. This movement of the ten bar 60 causes the carriage 43 of the elementary switch 40 to be moved longitudinally toward the right from its third off-normal position back into its normal position, due to the engagement between the latch 66 mounted on the carriage 43 and the slot 69 formed in the bar 70 rigidly secured by the strap 71 to the ten bar 60. When the finger 123^a on the lever 123 is engaged, the hundred bar 59 is moved longitudinally toward the right from its second off-normal position back into its normal position. This movement of the hundred bar 59 causes the finger 64^a on the lug 64 carried by the hundred bar 59 to disengage the latch 66 mounted on the carriage 42 of the elementary switch 40, thereby to allow the spring biased latch 66 to move out of the associated slot 69 formed in the bar 70 rigidly secured by the strap 71 to the ten bar 60. When the latch 66 mounted on the carriage 42 of the elementary switch 40 disengages the associated slot 69 formed in the bar 70, the carriage 42 of the elementary switch 40 is unlocked from the bar 70 and the elementary switch 40 is released. Thus, the switching unit is completely restored to its idle position and is again in condition to be reoperated simultaneously to select any particular lines in the odd and even groups in any one of the divisions of lines in the conductor bank 24.

Operation of the finder switch 301 and the distributor 302

Referring now more particularly to the operation of the apparatus illustrated in Figs. 17, 18 and 19, when a subscriber, such, for example, as the subscriber at the substation A, initiates a call over the line 304 to a second subscriber substation, such, for example, as the substation B, by lifting his receiver from its hook, a circuit is completed for energizing the lower winding of the line relay R350. This circuit extends from ground at RA341 by way of the line conductor C305 of the line 304, the bridge across C305 and C306 at the substation A, C306, RA342, RA352, RC353, the lower winding of R350, the control conductor C333 and RA391 to battery in the distributor and common equipment 302 associated with the hundred group of lines including the calling line 304. When energized over the above-traced circuit, the line relay R350 operates to complete at RA351 and RA352 a circuit for energizing its upper winding and to interrupt at RA352 and RC353 the circuit for energizing its lower winding. The latter circuit constitutes a holding circuit and extends from ground at RA341 by way of C305, the bridge across C305 and C306 at the substation A, C306, RA342, RA352, RA351, and the upper winding of R350 to battery. Upon operating, the line relay R350 also applies marking ground potential at RA354, RA355 and RA356 to the control conductors C330, C331 and C332, respectively. The calling line 304 corresponds to the third line in the third level or subgroup in the even or two-hundred group in the first division in the conductor bank 24, as will be more fully explained subsequently. The control conductor C330 is multiplied to the line circuits associated 70 75 80 85 90 95 100 105 110 115 120 125 130 135 140 145 150 155 160 165 170 175 180 185 190 195 200 205 210 215 220 225 230 with each subscriber line in the two-hundred group; the control conductor C331 is multiplied to the line circuits associated with each subscriber line in the third subgroup; and the control conductor C332 is multiplied to the line circuits associated with the third line in each subgroup. When ground potential is applied at RA354 to the control conductor C330, the control relay R390 is energized and operates to interrupt at RA391 the application of battery potential to the control conductor C333, the control conductor C333 being multiplied to the line circuits associated with each subscriber line in the two-hundred group in the first division. The removal of battery potential at RA391 from the control conductor C333 prevents a call initiated at any one of the substations associated with the remainder of the lines in the two-hundred group in the first division from interfering with the call initiated at the substation A, thereby rendering the distributor and common equipment 302 busy until the finder switch 301 of the link 501 seizes the calling line 304.

Upon operating, the control relay R390 also completes at RA392 an obvious circuit for energizing in series the control relay R400 and the operating motor M474 of the rotary switch 485, this circuit extending from ground at RA392 by way of the winding of R400, C494, the self-interrupting contacts 475 of the operating motor M474 and the winding of M474 to battery. Due to the high series resistance of this circuit, the operating motor M474 is not operated, but the control relay R400 is operated. Assuming that the finder-connector link 501 illustrated is the link assigned by the distributor 302 to the use of the calling line 304, the control relay R400, upon operating, marks, by the application of ground potential at RA401 to the control conductor C334, the finder switch 301 busy in the bank contacts of the other distributors. The path for marking the finder switch 301 busy extends from ground at RA401 by way of the wiper 486 and the contact terminating the control conductor C334 in the associated contact bank 487 of the rotary switch 485 to the control conductor C334, the control conductor C334 being multiplied to the corresponding contacts in the contact banks of the rotary switches in the other distributors. The control relay R400 also interrupts at RA402 and RC403 a point in a first circuit, traced hereinafter, for energizing the operating motor M474 of the rotary switch 485, prepares at RA402 and RC404 a second circuit, traced hereinafter, for energizing the operating motor M474, and completes at RA402 and RC404 a circuit for energizing the control relay R380 in the finder switch 301. The circuit for energizing the control relay R380 extends from ground at RA392 by way of the winding of R400, C494, RA402, RC404, the wiper 488 and the contact terminating the control conductor C335 in the associated contact bank 489 of the rotary switch 485, the control conductor C335 and the winding of R380 to battery. When energized over the above-traced circuit the control relay R380 operates to interrupt at RA381 a point in a primary circuit, traced hereinafter, for energizing the operating motor M3^a, corresponding to the operating motor M3 shown in Fig. 6, of the switching unit embodied in the finder switch 301. Upon operating, the control relay R380 also interrupts at RA382 a point in a circuit, traced hereinafter, for energizing the operating motor M2^a, corresponding to the operating motor M2 shown in Fig. 7, of the switching unit embodied in the finder switch 301.

Upon operating, the control relay R400 also completes at RA408 a point in a first circuit for energizing the operating motor M2^a, this circuit extending from the grounded control conductor C483 by way of the wiper 477 and the contact terminating the control conductor C336 in the associated contact bank 478 of the rotary switch 465, C336, RA408, C505, the wiper 492 and the contact terminating the control conductor C337 in the associated contact bank 493 of the rotary switch 485, the control conductor C337 and the winding of the operating motor M2^a to battery. When energized over the above-traced circuit the operating motor M2^a operates to condition the escapement control mechanism of the switching unit embodied in the finder switch 301 to be moved from its normal position into its first off-normal position, as previously explained. The control relay R400 also prepares at RA405 a second circuit, traced hereinafter, for energizing the operating motor M2^a, prepares at RA407 a point in a circuit, traced hereinafter, for energizing the operating motor M1^a, corresponding to the operating motor M1, shown in Fig. 7, of the switching unit embodied in the finder switch 301, and interrupts at RA409 a point in a reset circuit, traced hereinafter, for energizing the operating motor M479 in order to cause the operating motor M479 to drive the wipers 466 and 477 back into their normal or home positions.

Finally, the control relay R400 completes at RA406 a point in a circuit for energizing the operating motor M479, this circuit extending from ground at RA406 by way of RA411, and the winding of M479 to battery. When the operating motor M479 is energized over the above-traced circuit, it operates to complete at its armature 481 a circuit for energizing the control relay R410, this circuit extending from ground at the armature 481 by way of RA422, RC424, RA499 and the winding of R410 to battery. When energized over the above-traced circuit, the control relay R410 operates to interrupt at RA411 a point in the energizing circuit of the operating motor M479, causing the operating motor M479 to restore, thereby to drive the wipers 466 and 477 of the rotary switch 465 through a pawl and ratchet mechanism, not shown, from their normal positions one step in a counterclockwise direction. When the wiper 477 is moved from its normal position, it disengages the contact terminating the conductor C336 in the associated contact bank 478 of the rotary switch 465, thereby interrupting the previously traced circuit for energizing the operating motor M2^a. When the energizing circuit of the operating motor M2^a is interrupted, this operating motor restores to cause the escapement control mechanism of the switching unit embodied in the finder switch 301 to be moved from its normal into its first off-normal position, thereby to render the hundred bar of the switching unit operative, as previously explained. When the wiper 477 of the rotary switch 465 is moved from its normal position one step in a counterclockwise direction, it prepares a point in the reset circuit, traced hereinafter, which, when completed, causes the operating motor M479 to drive the wipers 466 and 477 back into their normal or home positions.

When the operating motor M479 restores it interrupts at its armature 481 a point in the energizing circuit of the control relay R410, causing the latter relay to restore. Upon restoring, the control relay R410 recompletes at RA411 the previously traced circuit for energizing the operating motor M479, causing the operating motor

M419 to recomplete the circuit for energizing the control relay R410. When the control relay R410 is energized, it reoperates to interrupt the energizing circuit of the operating motor M479, causing the operating motor M479 to restore and drive the wipers 466 and 477 of the rotary switch 465 a further step in a counterclockwise direction. The operating motor M479 and the control relay R410 continue to interact, as described above, to cause the operating motor M479 to drive the wipers 466 and 477 step by step in a counterclockwise direction at a relatively high speed until the wiper 466 is driven into engagement with the grounded contact 469 in the associated contact bank 467, at which time a circuit for energizing the transfer relay R420 is completed, this circuit extending from the grounded contact 469 by way of the wiper 466, the control conductor C482, the winding of R420 and the resistor 430 to battery. The number of steps between the contact engaged by the wiper 466 when it occupies its normal or home position and the contact 469 constitute an inactive group, and the wiper 466 is driven through this group of inactive steps at a relatively high speed in order to conserve time in causing the finder switch 301 to select the calling line 304. When energized over the above-traced circuit, the transfer relay R420 immediately operates to complete at RA425 an obvious holding circuit for itself, this circuit extending from ground at RA392 by way of RA425, the winding of R420 and the resistor 430 to battery. The transfer relay R420 also interrupts at RA422 and RC424 the original circuit for energizing the control relay R410, and completes at RA422 and RC423 an obvious circuit for energizing the slow-to-operate impulse relay R415, the latter circuit extending from ground at the armature 481 of the operating motor M479 by way of RA422, RC423 and the winding of R415 to battery. Further, the transfer relay R420 completes at RA421 the second circuit for energizing the operating motor M2^a, this circuit extending from ground at RA405 by way of RA421, C505, the wiper 492, the contact terminating the control conductor CS337 in the associated contact bank 493 of the rotary switch 485, the control conductor C337 and the winding of M2^a to battery. When energized over the above-traced circuit the operating motor M2^a operates to condition the escapement control mechanism of the switching unit embodied in the finder switch 301 to be moved into its second off-normal position.

Shortly after the relay R415 is energized over the above-traced circuit, the same, being of the slow-to-operate type, operates to complete at RA416 a circuit for energizing the control relay R410, this circuit extending from ground at RA416 by way of RA499 and the winding of R410 to battery. When energized over the above-traced circuit, the control relay R410 operates to interrupt at RA411 the energizing circuit of the operating motor M479, causing the operating motor M479 to restore and drive the wipers 466 and 477 a further step in a counterclockwise direction. Upon restoring, the operating motor M479 interrupts at its armature 481 the circuit for energizing the impulse relay R415, causing this relay to restore. Upon restoring the impulse relay R415 interrupts at RA416 the circuit for energizing the control relay R410, causing this relay to restore, and recomplete at RA411 the energizing circuit of the operating motor M479, causing the operating motor M479 to reoperate and recomplete at its armature 481 the energizing

circuit of the impulse relay R415. Shortly thereafter, the latter relay operates to recomplete at RA416 the circuit for energizing the control relay R410, causing the control relay R410 to reoperate. Upon reoperating, the control relay R410 again interrupts the energizing circuit of the operating motor M479, causing the operating motor M479 to restore and drive the wipers 466 and 477 a further step in a counterclockwise direction. The interaction of the operating motor M479, the control relay R410 and the impulse relay R415, causes the operating motor M479 to drive the wipers 466 and 477 step by step in a counterclockwise direction at a relatively slow speed until the wiper 466 engages the contact 470 in the associated contact bank 467, at which time a path for short-circuiting the transfer relay R420 is completed, this path extending from the upper terminal of the winding of R420 by way of the conductor C482, the wiper 466, the contact 470 and the conductor C484 to the lower terminal of the winding of R420. When this short-circuiting path is completed, the transfer relay R420 restores and interrupts at RA425 its holding circuit. Upon restoring, the transfer relay R420 also interrupts at RA422 and RC423 a point in the energizing circuit of the impulse relay R415, and completes at RA422 and RC424 a point in the circuit for energizing the control relay R410. Further, the transfer relay R420 interrupts at RA421 the second circuit for energizing the operating motor M2^a, causing the operating motor M2^a to restore and drive the escapement control mechanism of the switching unit embodied in the finder switch 301 into its second off-normal position, thereby to render operative the ten bar of the switching unit, as previously explained.

From the foregoing it is apparent that the impulse relay R415 interacts with the control relay R410 and with the operating motor M479, at this time, a number of times, depending upon the number of steps between the contact 469 and the contact 470 in the contact bank 467 of the rotary switch 465. In the present instance, there are two steps between the contacts 469 and 470, since the calling line is assumed to be included in the second one-hundred-line group. Thus, the impulse relay R415 is energized and deenergized two times successively. Each time the impulse relay R415 is energized it completes at RA417 a circuit for energizing the operating motor M1^a, this circuit extending from ground at RA417 by way of RA401, the wiper 490, the contact terminating the control conductor C338 in the associated contact bank 491 of the rotary switch 485, the control conductor C338 and the winding of M1^a to battery. Thus, two impulses are transmitted to the operating motor M1^a while the escapement control mechanism of the switching unit embodied in the finder switch 301 occupies its first off-normal position, thereby to cause the hundred bar of the switching unit to be moved from its normal position into its second off-normal position, as previously explained. The number of steps between the contacts 469 and 470 constitute an active group, and the wiper 466 is driven through this group of active steps at a relatively low speed, thereby to cause the series of impulses transmitted to the switching unit embodied in the finder switch 301 to be sufficiently long in order to allow the switching unit to operate properly in response thereto.

When the hundred bar of the switching unit is moved from its normal position into its first off-normal position, the contact set 245^a, correspond-

ing to the contact set 245 shown in Fig. 6, is moved from its normal position into its off-normal position. When the contact set 245^a is moved into its off-normal position, the contact spring 247^a engages the contact spring 248^a, thereby to apply multiple ground potential to the control conductor C334, and the contact spring 251^b engages the contact spring 252^a, thereby to apply ground potential to the conductor C339. The application of multiple ground potential to the control conductor C334 marks the finder switch 301 as busy in the bank contacts of the rotary switches of the distributors, and the application of ground potential to the conductor C339 prepares a point in the primary circuit for energizing the operating motor M3^a. At the conclusion of the first series of impulses transmitted to the operating motor M1^a, the hundred bar of the switching unit embodied in the finder switch 301 occupies either an odd or an even off-normal position, depending upon the number of impulses the first series of impulses comprises, thereby to cause the movement of the contact set 237^a, corresponding to the contact set 237 shown in Fig. 6, into its off-normal position. In the present instance, the first series of impulses comprises two impulses and the hundred bar of the switching unit is operated into its second off-normal position. Operation of the hundred bar of the switching unit into any even off-normal position moves the contact springs 241^a and 239^a of the contact set 237^a into engagement, thereby to prepare an obvious circuit for energizing the switching relay R360. On the other hand, operation of the hundred bar of the switching unit into any odd off-normal position moves the contact springs 241^a and 240^a of the contact set 237^a into engagement, thereby to prepare an obvious circuit for energizing the switching relay R370.

After the transfer relay R420 restores, the control relay R410 and the operating motor M479 again interact, as previously explained, to cause the operating motor M479 to drive the wipers 466 and 477 step by step in a counterclockwise direction at a relatively high speed, until the wiper 466 engages the contact 471 terminating the control conductor C331 in the associated contact bank 467 of the rotary switch 465, at which time a supplementary circuit for energizing the transfer relay R420 is completed. This circuit extends from ground at RA355 by way of the control conductor C331, the contact 471, the wiper 466, C482, the winding of R420 and the resistor 430 to battery. Upon operating, the transfer relay R420 again completes at RA425 its holding circuit, interrupts at RA422 and RC424 the original energizing circuit of the control relay R410, and completes at RA422 and RC423 the circuit for energizing the impulse relay RA415. Further, the transfer relay R420 recompletes at RA421 the second circuit for energizing the operating motor M2^a, thereby to cause the operating motor M2^a to condition the escapement control mechanism of the switching unit embodied in the finder switch 301 to be moved into its third off-normal position.

After the transfer relay R420 operates, the control relay R410, the impulse relay R415 and the operating motor M479 interact, as previously explained, to cause the operating motor M479 to drive the wipers 466 and 477 step by step in a counterclockwise direction at a relatively low speed, until the wiper 466 engages the contact 472 terminating the control conductor C484 in the associated contact bank 467, at which time a

supplementary path for short-circuiting the transfer relay R420 is completed. This short-circuiting path extends from the upper terminal of the winding of R420 by way of C482, the wiper 466, the contact 472 and C484 to the lower terminal of the winding of R420. When the transfer relay R420 is short-circuited, it restores, and upon restoring it interrupts at RA425 its holding circuit, interrupts at RA422 and RC423 the circuit for energizing the impulse relay R415, and completes at RA422 and RC424 the circuit for energizing the control relay R410. Further, the transfer relay R420 interrupts at RA421 the second circuit for energizing the operating motor M2^a, causing the operating motor M2^a to restore and drive the escapement control mechanism of the switching unit embodied in the finder switch 301 into its third off-normal position, thereby to render operative the unit bar of the switching unit, as previously explained.

From the foregoing it is apparent that the impulse relay R415 interacts with the control relay R410 and with the operating motor M479, at this time, a number of times, depending upon the number of steps between the contact 471 and the contact 472 in the contact bank 467 of the rotary switch 465. In the present instance, there are three steps between the contacts 471 and 472, since the calling line 304 is assumed to be included in the third ten-line subgroup of the second one-hundred-line group. Thus, the impulse relay R415 is energized and deenergized three times successively. Each time the impulse relay R415 is energized it completes at RA417 the above-traced circuit for energizing the operating motor M1^a. Thus, three impulses are transmitted to the operating motor M1^a while the escapement control mechanism of the switching unit embodied in the finder switch 301 occupies its second off-normal position, thereby to cause the ten bar of the switching unit to be moved from its normal position into its third off-normal position, as previously explained.

After the transfer relay R420 restores, the control relay R410 and the operating motor M479 again interact, as previously explained, to cause the operating motor M479 to drive the wipers 466 and 477 step by step in a counterclockwise direction at a relatively high speed, until the wiper 466 engages the contact 473 terminating the control conductor C332 in the associated contact bank 467 of the rotary switch 465, at which time a supplementary circuit for energizing the transfer relay R420 is completed. This circuit extends from ground at RA356 by way of the contact 473, the wiper 466, C482, the winding of R420 and the resistor 430 to battery. Upon operating, the transfer relay R420 again completes at RA425 its holding circuit, interrupts at RA422 and RC424 the original energizing circuit of the control relay R410, and completes at RA422 and RC423 the circuit for energizing the impulse relay R415. Further, the transfer relay R420 recompletes at RA421 the second circuit for energizing the operating motor M2^a, thereby to cause the operating motor M2^a to condition the escapement control mechanism of the switching unit embodied in the finder switch 301 to be moved into its fourth off-normal position.

After the transfer relay R420 operates, the control relay R410, the impulse relay R415 and the operating motor M479 interact as previously explained to cause the operating motor M479 to drive the wipers 466 and 477 step by step in a counterclockwise direction at a relatively low

speed, until the wiper 466 engages the contact 468 terminating the control conductor C484 in the associated contact bank 467, at which time a supplementary path for short-circuiting the transfer relay R420 is completed. This short-circuiting path extends from the upper terminal of the winding of R420 by way of C482, the wiper 466, the contact 468 and C484, to the lower terminal of the winding of R420. When the transfer relay R420 is short-circuited it restores, and upon restoring it interrupts at RA425 its holding circuit, interrupts at RA422 and RC423 the circuit for energizing the impulse relay R415, and prepares at RA422 and RC424 the circuit for energizing the control relay R410. Further, the transfer relay R420 interrupts at RA421 the second circuit for energizing the operating motor M2^a causing the operating motor M2^a to restore and drive the escapement control mechanism of the switching unit embodied in the finder switch 301 into its fourth off-normal position, thereby to render inoperative the unit bar of the switching unit, as previously explained.

From the foregoing it is apparent that the impulse relay R415 interacts with the control relay R410 and with the operating motor M479, at this time, a number of times, depending upon the number of steps between the contact 473 and the contact 468 in the contact bank 467 of the rotary switch 465. In the present instance, there are three steps between the contacts 473 and 468, since the calling line 304 is assumed to be the third line in the selected third subgroup of lines. Thus, the impulse relay R415 is energized and deenergized three times successively. Each time the impulse relay R415 is energized, it completes at RA417 the circuit for energizing the operating motor M1^a. Thus, three impulses are transmitted to the operating motor M1^a while the escapement control mechanism of the switching unit embodied in the finder switch 301 occupies its third off-normal position, thereby to cause the unit bar of the switching unit to be moved from its normal position into its third off-normal position, as previously explained.

At this time the wipers of the odd wiper set carried by the contact controlling member of the first elementary switch of the switching unit embodied in the finder switch 301 engage the third line in the third level or subgroup in the first group in the first division in the conductor bank 24; while the wipers of the even wiper set carried by this contact controlling member engage the third line in the third level or subgroup 55 in the second group in the first division in the conductor bank 24. More specifically, the positive, negative and control wipers 48^a, 49^a and 50^a, respectively, of the even wiper set carried by the contact controlling member of the first elementary switch of the switching unit engage the positive, negative and control conductors 311, 313 and 312, respectively, in the conductor bank 24, the last-mentioned conductors being adapted to be connected by way of the line circuit 300 to the calling line 304; while the positive, negative and control wipers 45^a, 46^a and 47^a, respectively, of the odd wiper set carried by this contact controlling member engage the positive, negative and control conductors 308, 310 and 70 309, respectively, in the conductor bank 24, the last-mentioned conductors being adapted to be connected by way of a line circuit to a corresponding subscriber line.

When the escapement control mechanism of the switching unit embodied in the finder switch

301 is driven into its fourth off-normal position, as previously explained, the contact set 268^a, corresponding to the contact set 268 shown in Fig. 7, is actuated to move the contact springs 261^a and 262^a into engagement, thereby to complete a circuit for energizing the switching relay R360. This circuit extends from ground at the contact spring 262^a by way of the contact springs 261^a, 241^a and 239^a, and the winding of R360 to battery. When energized over the above-traced 10 circuit, the switching relay R360 operates to connect at RA361, RA362 and RA363, the conductors C322, C323 and C324, respectively, of the auxiliary line 321 connected to the even wiper set of the first elementary switch of the switching unit embodied 15 in the finder switch 301 to the conductors C326, C327 and C328, respectively, of the trunk line 325. At this point it is noted that the wipers of the even wiper set of the first elementary switch are multiplied to the wipers of the even wiper sets 20 of the other elementary switches of the switching unit embodied in the finder switch 301. In a similar manner the wipers of the odd wiper set of the first elementary switch are multiplied to the wipers of the odd wiper sets of the other 25 elementary switches of the switching unit embodied in the finder switch 301. Thus, each even wiper set of the switching unit has access to the trunk line 325 by way of the auxiliary line 321 when the switching relay R360 is energized. 30 Similarly, each odd wiper set of the switching unit has access to the trunk line 325 by way of the auxiliary line 317 when the switching relay R370 is energized.

At this time, a loop is extended from the calling substation A by way of the subscriber line 304, the even wiper set of the first elementary switch, the auxiliary line 321 and the trunk line 325, to the line relay R520 in the connector switch 500, this circuit extending from ground at the lower terminal of the upper winding of R520 by way of the upper winding of R520, the conductor C641, RC556, RA555, the line conductor C326, RA361, C322, the wiper 48^a, the conductor 311, the line conductor C305, the bridge across C305 and C306 at the calling substation A, the line conductor C306, the conductor 313, the wiper 49^a, C324, RA363, the line conductor C328, RA552, RC553 and the lower winding of R520 to battery at the upper terminal of the lower winding of R520. When energized over the above-traced 45 circuit, the line relay R520 operates to complete at RA521 and RC522 an obvious circuit for energizing the hold relay R530, this circuit extending from ground at RA521 by way of RC522 and the winding of R530 to battery. When energized over the above-traced circuit, the hold relay R530 operates to apply at RA531 ground potential to the control conductor C327 of the trunk line 325, thereby further to mark the finder switch 301 60 as busy in the bank contacts of the rotary switches of the distributors.

It is noted that when the wiper 466 is driven by the operating motor M479 into engagement with the contact 468 terminating the control conductor C484 in the associated contact bank 467, the control cam 504 is actuated to move the contact springs 502 and 503 into engagement, thereby to complete a circuit for energizing the control relay R498. This circuit extends from ground at RA392 by way of C497, the contact springs 502 and 503, C495 and the winding of R498 to battery. When energized over the above-traced circuit the control relay R498 operates to interrupt at RA499 a point in the energizing 75

circuit of the control relay R410. Thus, the energizing circuit of the control relay R410 is not recompleted upon the restoration of the transfer relay R420 at the conclusion of the third series of impulses, and the rotary switch 465 is not further operated at this time.

The application of ground potential, at RA531, to the control conductor C327 retains the control relay R390 in operated position and completes a circuit for energizing the operating motor M474 of the rotary switch 485 of the distributor 302 illustrated. The latter circuit extends from the grounded control conductor C327 by way of the control conductor C335, the contact terminating the control conductor C335 in the contact bank 489 of the rotary switch 485, the wiper 488, RC404, RA402, C494, the self-interrupting contacts 475 of the operating motor M474, and the winding of M474 to battery. The application of ground potential to the control conductor C327 also results in the short-circuiting of the control relay R400, causing this relay to restore. When the control relay R400 restores, the link test circuit is transferred to the test wiper 486 of the switch 485 through the engagement of RA402 and RC403. When energized over the circuit just traced, the operating motor M474 operates to drive the wipers 486, 488, 490 and 492 of the rotary switch 485 one step in a clockwise direction, causing the wiper 486 to engage a contact in the contact bank 487 terminating a control conductor associated with the next link. If the next link is idle no potential appears upon the control conductor thereof, causing further operation of the operating motor M474 to be arrested. On the other hand, if the next link is busy, ground potential appears upon the control conductor thereof, causing the circuit for short-circuiting the control relay R400 and the circuit for energizing the operating motor M474 to be recompleted. Thus, the control relay R400 is prevented from reoperating and the operating motor M474 continues to operate buzzer fashion until the wiper 486 engages a contact in the contact bank 487 of the rotary switch 485 terminating a control conductor associated with an idle link. The relay R400 is reenergized in series with the winding of the operating motor M474 when an idle link is found. Thus, the distributor 302 operates to find an idle link for the use of the next calling line in the two-hundred group immediately the link 501 seizes a calling line in this group.

The application of ground potential to the control conductor C327 of the trunk line 325 also completes a circuit for energizing the cut-off relay R340, this circuit extending from the grounded control conductor C327 by way of RA362, C323, the wiper 50^a, the conductor 312, the control conductor C307 and the winding of R340 to battery. When energized over the above-traced circuit, the cut-off relay R340 operates to interrupt at RA341 and RA342 the holding circuit of the line relay R350, causing the latter relay to restore. Upon restoring, the line relay R350 interrupts at RA354, RA355 and RA356 the paths for applying marking or ground potential to the control conductors C330, C331 and C332, respectively.

When ground potential is removed from the control conductor C330, the control relay R390 restores and applies battery potential at RA391 to the control conductor C333. The application of battery potential to the control conductor C333 marks the distributor and common equipment 70 302 as idle, rendering the same accessible to the

other subscriber lines in the two-hundred group in order to assign idle finder-connector links thereto. Upon restoring, the control relay R390 interrupts at RA392 a point in the circuit for energizing the control relay R498, causing the latter relay to restore and prepare at RA499 a point in the circuit for energizing the control relay R410. Upon restoring, the control relay R390 also interrupts at RA392 the circuit for energizing in series the control relay R400 and the operating motor M474, causing the latter relay to restore. Upon restoring, the control relay R400 completes at RA403 a circuit for energizing the operating motor M479, this circuit extending from the grounded control conductor C483 by way of the wiper 477 of the rotary switch 465, the multiplied contacts of the associated contact bank 478, RA409, the self-interrupting contacts 480 of the operating motor M479 and the winding of M479 to battery. When energized over the above-traced circuit, the operating motor M479 operates buzzer fashion to drive the wipers 466 and 477 in a counterclockwise direction into their normal or home positions, at which time the wiper 477 disengages the multiplied contacts of the contact bank 478 of the rotary switch 465, thereby completely interrupting the energizing circuit of the operating motor M479. When the wipers 466 and 477 are driven into their normal or home positions, the control cam 504 is actuated to move the contact springs 502 and 503 into disengagement, thereby to interrupt a further point in the energizing circuit of the control relay R498. At this time the distributor and common equipment 302 is completely released and the distributor thereof has assigned an idle finder-connector link to the use of the next calling line in the two-hundred group. Also, upon restoring, the control relay R400 prepares at RA402 and RC403 the first circuit, traced hereinafter, for energizing the operating motor M474 of the rotary switch 485, in a manner more fully described subsequently.

In the foregoing description it was assumed that the distributor 302 selected the finder-connector link 501 for the use of the calling line 304 before the call was initiated on this line. If, prior to the initiation of the call on the subscriber line 304, another of the distributors had seized the link 501, the distributor 302 would have immediately been set into operation to find a further idle link, as the seizure of the link 501 by the other distributor would have caused the contact set 245^a to be moved into its off-normal position, thereby to complete the first circuit for energizing the operating motor M474. This circuit extends from the grounded contact spring 247^a by way of the contact spring 248^a, the control or test conductor C334, the contact in the contact bank 487 of the rotary switch 485 terminating the control conductor C334, the wiper 486, RC403, RA402, C494, the self-interrupting contacts 475 of the operating motor M474, and the winding of M474 to battery. When energized over the above-traced circuit, the operating motor M474 operates to drive the wipers 486, 488, 490 and 492 of the rotary switch 485 one step in a clockwise direction. If the next link is idle the control conductor thereof terminating at the engaged contact in the contact bank 487 of the rotary switch 485 has no ground potential thereon and the first circuit for energizing the operating motor M474 is interrupted, causing further operation of the operating motor M474 to be arrested. On the other hand, 75

if the next link is busy, ground potential appears upon the control conductor thereof, due to the fact that the contact set in the finder switch of the next link corresponding to the contact set 5 245^a occupies an off-normal position, causing ground potential to be applied to the control conductor thereof and the consequent recompletion of the first circuit for energizing the operating motor M474. The operating motor M474 continues to operate buzzer fashion until the wiper 486 engages a contact in the contact bank 487 terminating a control conductor associated with an idle finder-connector link. Thus, the distributor 302 assigns an idle finder-connector link 10 15 to the use of the next calling line in the two-hundred group immediately an assigned finder-connector link is seized. Hence, this distributor is of the fully directive type.

Attention is also directed to the fact that, 20 should another distributor seize the link 501 just prior to the operation of the control relay R400 to mark the link 501 busy at RA401 and subsequent to the operation of the line relay R350 to complete at RA354 the energizing circuit of the 25 control relay R390, the control relay R400 is short-circuited upon the operation of the control relay R390. This short-circuiting path extends from ground at RA392 to the lower terminal of the winding of R400 and from the grounded control conductor C334 by way of the contact in the contact bank 487 terminating the control conductor C334, the wiper 486, RC403, RA402 and C494 to the upper terminal of the winding of 30 R400. At this time the operating motor M474 is energized by way of the first circuit, as previously explained, and operates to drive the wipers 486, 488, 490 and 492 in a clockwise direction step by step until an idle link is found. When an idle link is found, the path for short-circuiting R400 is interrupted at the contact set of the 35 finder switch of the idle link, corresponding to the contact set 245^a, whereupon R400 operates as previously explained.

46 Operation of the connector switch 500

At this point it is noted that the switching unit embodied in the connector switch 500 departs slightly from the construction of the switching unit embodied in the finder switch 301, previously 40 described, in two particulars. In the first place, the odd wiper set carried by the contact controlling member of at least one of the elementary switches of the switching unit is provided with an extra wiper. In the switching unit embodied in the connector switch 500, this extra wiper of the odd wiper set of the elementary switch illustrated is indicated at 512. This extra wiper 512 in the odd wiper set is utilized in a manner more fully 45 explained subsequently in connection with the operation of the connector switch 500 to find an idle line in a small group of P. B. X. lines. In the second place, the escapement control mechanism incorporated in the switching unit embodied in the connector switch 500 is slightly different from 50 the escapement control mechanism previously described, in that the first off-normal position thereof constitutes a home position such that the hundred bar of this switching unit is rendered 55 operative when the switching unit occupies an idle position. This may be readily accomplished in an obvious manner by so constructing and arranging the escapement control mechanism 154 incorporated in the switching unit embodied in the connector switch 500, that the four equally 60 spaced-apart projections on the periphery of each

of the cam members 157, 158 and 159 therein are spaced from each other by a distance equal to four steps of the ratchet wheel 155 instead of five steps, as previously described.

At this time, the finder switch 301 of the link 5 501 has seized the calling line 304, causing the line relay R520 and the hold relay R530 in the connector switch 500 of the link 501 to be operated, as previously noted. The connector switch 500 is thus conditioned to be responsive to the impulses comprising the first digit dialed at the calling substation A. As previously pointed out, the hold relay R530 operates to apply at RA531 ground potential to the control conductor C327 of the trunk line 325. Also, the hold relay R530 10 prepares at RA532 and RC533 an impulsive circuit for energizing in series the control relay R540 and the operating motor M1^b, corresponding to the operating motor M1 shown in Fig. 7. The impulsive circuit for the control relay R540 and the 15 operating motor M1^b is completed at the beginning of the first impulse of the first series of impulses dialed at the calling substation A and when the line relay R520 restores. This circuit extends from ground at RA521 by way of RC523, 20 RA522, RC533, the winding of R540, RA592, RA571 and the winding of M1^b to battery. When energized over the above-traced circuit, the operating motor M1^b operates to cause the hundred 25 bar of the switching unit embodied in the connector switch 500 to be moved from its normal position into its first off-normal position, as previously explained. Also, the control relay R540 is operated to complete at RA542 a circuit for 30 energizing the control relay R560, this circuit extending from ground at RA542 by way of the winding of R560 to battery. When energized over the above-traced circuit the control relay R560 operates to complete at RA566 a first circuit for 35 energizing the operating motor M2^b, corresponding to the operating motor M2 shown in Fig. 7, this first energizing circuit extending from ground at RA566 by way of the winding of M2^b to battery. When energized over the above-traced circuit, the operating motor M2^b operates to condition 40 the escapement control mechanism of the switching unit embodied in the finder switch 500 to be moved from its first off-normal into its second off-normal position; the first off-normal position of this escapement control mechanism constitutes a home position thereof, as previously 45 noted.

Further, the control relay R540 interrupts at RA543 a point in a circuit, traced hereinafter, for 50 energizing the control relay R160. Also the control relay R560 operates to complete at RA561 a branch path in the circuit for energizing the operating motor M1^b, and to prepare at RA562 and RA563 a point in a circuit, traced hereinafter, for 55 energizing the busy relay R570. During each impulse of the first series of impulses the operating motor M1^b is energized in the above-described manner so that at the conclusion of the first digit the hundred bar of the switching unit occupies 60 an off-normal position, causing the illustrated 65 elementary switch of the switching unit to be rendered operative, this elementary switch having access to the division of conductors in the conductor bank 24 including the line to which the called line 670 is connected. During the first 70 series of impulses, each time the bridge at the substation A across the line conductors C305 and C306 of the calling line 304 is interrupted, the line relay R520 restores, causing the control relay R540 and the operating motor M1^b to be energized 75

in series, as previously explained. Also, each time the bridge at the substation A across the line conductors C305 and C306 is completed, the line relay R520 reoperates and completes the circuit for energizing the hold relay R530. Thus, the hold relay R530 and the control relays R540 and R560 remain operated during the impulsive period due to their slow-to-release characteristics.

When the hundred bar of the switching unit embodied in the connector switch 500 is moved from its normal position into its first off-normal position, the contacts of the set 245^b, corresponding to the contact set 245 shown in Fig. 6, are moved into the off-normal position. When this occurs, the contact springs 251^b and 252^b are moved into engagement, thereby to prepare a primary circuit, traced hereinafter, for energizing the operating motor M3^b, corresponding to the operating motor M3 shown in Fig. 6. At the conclusion of the first series of impulses, the hundred bar of the switching unit occupies an off-normal position which is either odd or even, depending upon the number of impulses the first series of impulses comprises. In the present instance, the first series of impulses must comprise an even number of impulses as the calling line 670 is connected to a line in the conductor bank 24 disposed in an even group in the associated division of lines. Thus, the contact set 237^b, corresponding to the contact set 237 shown in Fig. 6, is moved from its normal position into its off-normal position to cause the contact spring 241^b to engage the contact spring 239^b, thereby to complete an obvious circuit for energizing the switching relay R600. This circuit extends from ground at the contact spring 241^b by way of the contact spring 239^b and the winding of R600 to battery. When energized over the above-traced circuit, the switching relay R600 operates to cause the armatures RA601, RA604, and RA607 to disengage the contacts RC602, RC605 and RC609, respectively, and to engage the contacts RC603, RC606 and RC608, respectively. The engagement between the armature RA604 and the contact RC606 prepares a point in a circuit, traced hereinafter, for testing the idle or busy condition of the called line 670, in a manner more fully described subsequently.

Shortly following the conclusion of the first digit, the control relay R540 restores. Upon restoring, the control relay R540 interrupts at RA542 the circuit for energizing the control relay R560, and the latter relay restores shortly thereafter. Upon restoring, the control relay R560 interrupts at RA566 the first series for energizing the operating motor M2^b, causing the same to restore. Upon restoring, the operating motor M2^b drives the escapement control mechanism of the switching unit embodied in the connector switch 500 into its second off-normal position, thereby to render operative the ten bar of the switching units, as previously explained. At this time the connector switch 500 is conditioned to be responsive to the second series of impulses comprising the second digit dialed at the calling substation A.

At the beginning of the first impulse of the second series of impulses dialed at the calling substation A and when the line relay R520 restores, the circuit for energizing in series the control relay R540 and the operating motor M1^b is completed at RA521 and RC523. When thus energized, the operating motor M1^b operates to cause the ten bar of the switching unit embodied in the connector switch 500 to be moved from its normal position into its first off-normal position.

When the control relay R540 is thus energized it operates to complete at RA542 the circuit for energizing the control relay R560, thereby to cause operation of R560. Upon operating, the control relay R560 completes at RA566 the first circuit for energizing the operating motor M2^b. When thus energized, the operating motor M2^b operates to condition the escapement control mechanism of the switching unit embodied in the connector switch 500 to be moved into its third off-normal position. During each impulse of the second series of impulses the operating motor M1^b is energized in the above-described manner so that at the conclusion of the second digit the ten bar of the switching unit occupies an off-normal position, causing the illustrated elementary switch of the switching unit to select the level or subgroup of lines in the conductor bank 24 to which the called line 670 is connected. Shortly following the conclusion of the second digit, the control relay R540 restores to cause the control relay R560 to restore shortly thereafter. Upon restoring, the control relay R560 interrupts at RA566 the first circuit for energizing the operating motor M2^b, causing the same to restore. Upon restoring, the operating motor M2^b drives the escapement control mechanism of the switching unit embodied in the connector switch 500 into its third off-normal position, thereby to render operative the unit bar of the switching unit, as previously explained. At this time, the connector switch 500 is conditioned to be responsive to the third series of impulses comprising the third and final digit dialed at the calling substation A.

At the beginning of the first impulse of the third series of impulses dialed at the calling substation A and when the line relay R520 restores, the circuit for energizing in series the control relay R540 and the operating motor M1^b is completed at RA521 and RC523. When thus energized, the operating motor M1^b operates to cause the unit bar of the switching unit embodied in the connector switch 500 to be moved from its normal position into its first off-normal position. When the control relay R540 is thus energized, it operates to cause the control relay R560 to operate. Upon operating, the control relay R560 completes at RA566 the first circuit for energizing the operating motor M2^b. When thus energized, the operating motor M2^b operates to condition the escapement control mechanism of the switching unit embodied in the connector switch 500 to be moved into its fourth off-normal position. During each impulse of the third series of impulses, the operating motor M1^b is energized in the above-described manner so that at the conclusion of the third digit the unit bar of the switching unit occupies an off-normal position, causing the illustrated elementary switch of the switching unit to select the line in the conductor bank 24 to which the called line 670 is connected. At this time the wipers of the even wiper set carried by the contact controlling member of the elementary switch illustrated of the switching unit embodied in the connector switch 500 engage the line in the even group in the division in the conductor bank 24 to which the called line 670 is connected; while the wipers of the odd wiper set carried by this contact controlling member engage the corresponding line in the odd group in the division in the conductor bank 24. More specifically, the positive, negative and control wipers 45^b, 46^b and 47^b, respectively, of the even wiper set of the illustrated element switch of the switching unit

engage the positive, negative and control conductors 508, 506 and 507, respectively, of the selected line in the even group of lines in the conductor bank 24, the last-mentioned line being connected by way of the line circuit 675 to the called line 670; while the positive, negative and control wipers 48^b, 49^b and 50^b, respectively, of the odd wiper set of the illustrated elementary switch engage the positive, negative and control conductors 713, 710 and 711, respectively, of the selected line in the odd group of lines in the conductor bank 24, the last-mentioned conductors being connected by way of a line circuit to a corresponding line. At this point it is noted that the wipers of the even wiper set of the illustrated elementary switch are multiplied to the wipers of the even wiper sets of the other elementary switches of the switching unit embodied in the connector switch 500. In a similar manner the wipers of the odd wiper set of the illustrated elementary switch are multiplied to the wipers of the odd wiper sets of the other elementary switches of the switching unit embodied in the connector switch 501. Thus, each even wiper set of the switching unit has access to the trunk line 325 when the switching relay R600 is energized. Similarly, each odd wiper set of the switching unit has access to the trunk line 325 when the switching relay R600 is restored.

In the event that the subscriber line 670 is busy, ground potential appears upon the control conductor C674 thereof, whereupon the busy relay R570 is energized over a circuit extending from the grounded control conductor C674 by way of the conductor 507, the wiper 47^b, RC606, RA604, RA562, RA563 and the winding of R570 to battery. When energized over the above-traced circuit, the busy relay R570 operates to interrupt at RA571 a further point in the circuit for energizing in series the control relay R540 and the operating motor M1^b, thereby to prevent further operation of the operating motor M1^b. Also, the busy relay R570 prepares at RA571' and RC572 a point in a holding circuit, traced hereinafter, for itself, interrupts at RA571' and RC573 a point in a circuit, traced hereinafter, for operating the switching-through relay R590, and completes at RA574 a point in a path, traced hereinafter, for applying busy tone current to the loop extending to the calling substation A.

Shortly following the conclusion of the third digit, the control relay R540 restores to cause the control relay R560 to restore shortly thereafter. Upon restoring, the control relay R560 interrupts at RA566 a point in the first circuit for energizing the operating motor M2^b causing the operating motor to restore. Upon restoring, the operating motor M2^b drives the escapement control mechanism of the switching unit embodied in the connector switch 500 into its fourth off-normal position, thereby to render inoperative the unit bar of the switching unit, as previously explained. Upon restoring, the control relay R560 also interrupts at RA561 a further point in the circuit for energizing in series the control relay R540 and the operating motor M1^b, interrupts at RA562 and RA563 a point in the original operating circuit of the busy relay R570, prepares at RA562 and RC565 a point in a circuit, traced hereinafter, for energizing the switching-through relay R590, and completes at RA563 and RC564 the holding circuit for the busy relay R570, the latter circuit extending from the grounded control conductor C327 by way of RA571', RC572, RC564, RA563

and the winding of R570 to battery. The holding circuit of the busy relay R570 is completed before the operating circuit thereof is interrupted.

The path for applying busy tone current to the loop extending to the calling substation A extends from pulsating ground potential upon the busy conductor C625 by way of RA574, the voice coupling condenser 623, the line conductor C326 of the trunk line 325, the operated finder switch 301, the line conductor C305, the bridge including the receiver of the telephone instrument across the line conductors C305 and C306 at the calling substation A, C306, the operated finder switch 301, the line conductor C328 of the trunk line 325, RA352, RC353, and the lower winding of the line relay R325 to battery. The resulting busy tone indicates to the calling subscriber that the desired connection cannot immediately be completed.

In the event the called line 670 is idle, battery potential appears upon the control conductor C674 thereof, this battery potential being derived at the upper terminal of the cut-off relay R660, causing the busy relay R570 to be short-circuited, this short-circuiting path extending from battery at the lower terminal of the winding of R660 by way of the winding of R660, the control conductor C674, the conductor 507, the wiper 47^b, RC606, RA604, RA562, RA563 and the winding of R570 to battery. Thus, the busy relay R570 does not operate, and shortly following the conclusion of the third digit and when the control relays R540 and R560 restore, the circuit for energizing the switching-through relay R590 is completed at RA562 and RC565. This circuit extends from battery at the lower terminal of the winding of the cut-off relay R660, by way of the winding of R660, the control conductor C674, the conductor 507, the wiper 47^b, RC606, RA604, RA562, RC565, the lower winding of R590, RC573 and RA571' to the grounded control conductor C327.

When energized over the above-traced circuit, the switching-through relay R590 operates to complete at RA591 and RA595 points in a circuit, traced hereinafter, for projecting ringing current over the loop extending to the called substation B, to complete at RA596 a circuit, traced hereinafter, for returning ring-back tone current over the loop extending to the calling substation A, and to interrupt at RA592 a further point in the circuit for energizing in series the control relay R540 and the operating motor M1^b, thereby to prevent further operation of the operating motor M1^b. Further, the switching-through relay R590 completes at RA594 a holding circuit for itself extending from the grounded control conductor C327 by way of RA594 and the upper winding of R590 to battery, and connects the control conductor C674 to the grounded control conductor C327. When the grounded control conductor C327 is connected to the control conductor C674, the cut-off relay R660 is energized and operates. Upon operating, the cut-off relay R660 interrupts at RA661 and RA662 points in the circuit for energizing the line relay R650, thereby to prevent the operation of the line relay R650 when the call is answered at the called substation B and the consequent seizure of the called line 670 by the finder switch of a link assigned thereto.

The circuit for projecting ringing current over the loop extending to the called substation B extends from the ungrounded terminal of a grounded ringing current transformer winding, not shown, by way of the conductor C624, the 75

lower winding of R580, RC582, RA581, RA591, RA601, RC603, the wiper 46^b, the conductor 506, the line conductor C612, the series connected condenser and ringer bridged across the line conductors C672 and C673 at the called substation R, C673, the conductor 508, the wiper 45^b, RC608, RA607, RA595, RA585 and RC587 to ground. The ringing current projected over the above-traced circuit to the called substation B 5 operates the ringer thereat, thereby giving the called party an audible signal that the substation B is being called. A portion of this current is returned through the condenser 597 and the voice coupling condenser 622 over the loop 10 extending to the calling substation A in order to indicate to the calling party that the called substation B is being rung. The circuit traversed by the ring-back tone current extends from the ungrounded terminal of the grounded ringing current 15 transformer winding by way of the conductor C624, the lower winding of R580, RC582, RA581, RA596, the condenser 597, the conductor C620, the voice coupling condenser 622, the line conductor C328 of the trunk line 325, the operated 20 finder switch 301, the line conductor C306, the bridge including the receiver of the telephone instrument across the line conductors C306 and C305, C305, the operated finder switch 301, the line conductor C326 of the trunk line 325, RA555, 25 RC556, and the upper winding of the line relay R520 to ground. 30

When the call is answered at the called substation B by removing the receiver of the telephone instrument thereat from its associated hook, a low resistance circuit is completed for 35 energizing the ring cut-off relay R580, this circuit being the same as the circuit for projecting ringing current to the substation B, except for the low resistance path bridged across the line conductors C672 and C673 of the called line 670 40 at the substation B in parallel with the bridged ringer and condenser thereat. Shortly thereafter the ring cut-off relay R580, being of the slow-to-operate type, is operated to interrupt at RA581 and RC582 the circuit for returning ring-back tone current through the condenser 597 and the voice coupling condenser 622 to the calling substation A, and to interrupt at RA581, RC582, RA585, 45 RC587, the circuit for projecting ringing current to the called substation B. Also, the ring cut-off relay R580 completes at RA584 an obvious holding circuit for itself extending from the grounded control conductor C327 by way of RA584 and the upper winding of R580 to battery. Further, the ring cut-off relay R580 completes at RA581, RC583 and RA585, RC586, 50 a loop circuit between the calling substation A and the called substation B, including the voice coupling condensers 622 and 623. When the loop is completed to the called substation B, the battery reversing relay R550 is energized over a circuit extending from ground at the upper terminal of the upper winding of R550 by way of the upper winding of R550, C621, RC586, RA585, RA595, RA607, 55 RC608, the wiper 45^b, the conductor 508, C673, the bridge across the line conductors C673 and C672 at the called substation B, C672, the conductor 506, the wiper 46^b, RC603, RA601, RA591, RA581, RC583, C620 and the lower winding of 60 R550 to battery. When energized over the above-traced circuit, the battery reversing relay R550 operates to reverse the battery applied to the line conductors C328 and C326 of the trunk line 325 extending by way of the operated finder switch 65 70 75 301 to the calling substation A. This reversal of

battery potential, as applied to the line conductors C326 and C328 of the trunk line 325 extending by way of the operated finder switch 301 to the calling substation A, may be utilized to operate a register or a coin collecting or other device, associated with the calling substation A. At this time, talking battery is supplied to the loop extending to the calling substation A through the windings of the line relay R520, and talking battery is supplied to the loop extending to the called 10 substation B through the windings of the battery reversing relay R550. 15

Release of the finder switch 301 and the connector switch 500

The release of the established connection, including the operated finder switch 301 and the operated connector switch 500, is under the control of the calling party. In releasing the established connection, the calling party replaces 20 the receiver of the telephone instrument at the substation A upon its associated hook, thereby to interrupt the loop extending from the substation A and including the line relay R520. When this loop is interrupted, the line relay R520 restores to interrupt at RA521 and RC522 the operating circuit of the hold relay R530 and to prepare at RA521 and RC523 a point in a primary circuit, traced hereinafter, for energizing the operating motor M3^b, corresponding to the operating motor M3 shown in Fig. 6. Shortly thereafter the hold relay R530 restores and 25 interrupts at RA521 the path for applying ground potential to the control conductor C327 of the trunk line 325, and completes at RA532 and RC534 the primary circuit for energizing the operating motor M3^b. The primary circuit for energizing the operating motor M3^b extends from ground at RA521 by way of RC523, RA532, 30 RC534, the contact springs 252^b and 251^b, and the winding of M3^b to battery. When energized over the above-traced circuit, the operating motor M3^b is operated, thereby to cause the unit, ten and hundred bars of the switching unit embodied in the connector switch 500 to be restored to their 35 normal positions in the manner previously described. Shortly after the operating motor M3^b begins to operate, the contact set 222^b, corresponding to the contact set 222, shown in Fig. 6, is actuated to move the contact springs 223^b and 224^b into engagement, thereby to complete an obvious secondary circuit for energizing the operating motor M3^b. When the operating motor M3^b returns the ten and hundred bars back 40 into their normal positions, the contact set 245^b is moved into its normal position. When the contact set 245^b is moved into its normal position, the contact springs 251^b and 252^b are disengaged, thereby interrupting the primary circuit for energizing the operating motor M3^b. 45 When the operating motor M3^b rotates the reset mechanism incorporated in the switching unit embodied in the connector switch 500 exactly one revolution, the contact set 222^b is actuated to move the contact springs 223^b and 224^b into disengagement, thereby to interrupt the secondary circuit for energizing the operating motor M3^b. At this time, further operation of the operating motor M3^b is arrested and the switching unit embodied in the connector switch 500 is completely 50 restored to its idle position. 55

Upon restoring, the hold relay R530 also completes at RA532 and RC534 a second circuit extending by way of the contact set 270^b, corresponding to the contact set 270 shown in Fig. 7, 75

and the contact set 280^b, corresponding to the contact set 280 shown in Fig. 7, for energizing the operating motor M2^b. More specifically, this circuit extends from ground at RA521 by way of 5 RC523, RA532, RC 534, the contact springs 271^b and 272^b, the contact springs 281^b and 282^b, and the winding of M2^b to battery. When energized over the above-traced circuit, the operating motor M2^b conditions the escapement control mechanism 10 of the switching unit embodied in the connector switch 500 to be moved into its fifth off-normal position. It is noted that this position of this escapement control mechanism corresponds to the first off-normal position thereof, and accordingly constitutes a home position thereof. Also, upon operating, the operating motor M2^b moves the contact springs 281^b and 282^b into disengagement, thereby to interrupt its second energizing circuit. When the second energizing 15 circuit of the operating motor M2^b is interrupted, the operating motor M2^b restores, thereby to drive the escapement control mechanism of the switching unit into its fifth off-normal position. When the escapement control mechanism is driven into 20 its fifth off-normal position, the contact springs 271^b and 272^b are moved into disengagement, thereby to interrupt a further point in the second energizing circuit of the operating motor M2^b and to arrest further operation thereof. When 25 the hundred bar of the switching unit is moved back into its normal position, the contact set 237^b is moved into its normal position, causing the contact spring 241^b to disengage the contact spring 239^b, thereby to interrupt the circuit for 30 energizing the switching relay R600, causing this relay to restore. When the switching relay R600 restores, the armatures RA601, RA604 and RA607 35 disengage the contacts RC603, RC606 and RC608, respectively, and reengage the contacts RC602, RC605 and RC609, respectively.

When ground potential is removed at RA 531 from the control conductor C327, the holding circuits of the ring cut-off relay R580 and the switching-through relay R590 are interrupted, 45 causing these relays to restore. At this time, the connector switch 500 is completely released for further use.

When ground potential is removed from the control conductor C327, the control relay R380 50 in the finder switch 301 restores and completes at RA381 the primary circuit for energizing the operating motor M3^a, this circuit extending from ground at the contact spring 252^a by way of the contact spring 251^a, RA381 and the winding of M3^a to battery. When energized over the above-traced circuit, the operating motor M3^a operates to return the unit, ten and hundred bars of the switching unit embodied in the finder switch 301 back into their normal positions. Shortly 55 after the operating motor M3^a begins to operate, the contact set 222^a, corresponding to the contact set 222 shown in Fig. 6, is actuated to move the contact springs 223^a and 224^a into engagement, thereby to complete an obvious secondary 60 circuit for energizing the operating motor M3^a. When the operating motor M3^a returns the hundred and ten bars back into their normal positions, the contact set 245^a is moved into its normal position. When the contact set 245^a is moved 65 into its normal position, the contact springs 252^a and 251^a are disengaged, thereby to interrupt the primary circuit for energizing the operating motor M3^a. At the springs 247^a and 248^a ground is removed from the control conductor C334, there- 70 by to mark the link as idle in the bank contacts 75

of the rotary switch 485. When the operating motor M3^a rotates the reset mechanism incorporated in the switching unit embodied in the finder switch 301 exactly one revolution, the contact set 222^a is actuated to move the contact springs 223^a and 224^a into disengagement, thereby to interrupt the secondary circuit for energizing the operating motor M3^a and to arrest further operation thereof. At this time, the switching unit embodied in the finder switch 301 is restored to 10 its idle position.

When the control relay R380 restores it also completes at RA382 a circuit extending by way of the contact set 270^a, corresponding to the contact set 270 shown in Fig. 7, and the contact set 15 280^a, corresponding to the contact set 280 shown in Fig. 7, for energizing the operating motor M2^a. More specifically, this circuit extends from ground at RA382 by way of the contact springs 272^a and 271^a, the contact springs 281^a and 282^a, 20 and the winding of M2^a to battery. When energized over the above-traced circuit, the operating motor M2^a operates to condition the escapement control mechanism of the switching unit to be moved into its fifth off-normal position, this 25 position of the escapement control mechanism constituting a normal position thereof, as previously explained. Also, upon operating, the operating motor M2^a moves the contact springs 281^a and 282^a into disengagement, thereby to interrupt the circuit for energizing the operating motor M2^a, causing the operating motor M2^a to 30 restore. Upon restoring, the operating motor M2^a drives the escapement control mechanism of the switching unit embodied in the finder switch 301 into its fifth off-normal position. When the escapement control mechanism is driven into its fifth off-normal position, the contact sets 260^a and 270^a are actuated to move the contact springs 261^a and 262^a into disengagement and 35 to move the contact springs 271^a and 272^a into disengagement. When the contact springs 271^a and 272^a are disengaged, the circuit for energizing the operating motor M2^a is interrupted in order to prevent further operation thereof. When 40 the contact springs 261^a and 262^a are disengaged, the circuit for energizing the switching relay R360 is interrupted, causing the latter relay to restore. Upon restoring, the switching relay R360 45 disconnects the auxiliary line 321 connected to the even wiper set of the switching unit embodied in the finder switch 301 from the trunk line 325. When the hundred bar of the switching unit is returned to its normal position, the contact set 55 237^a is returned to its normal position, causing the contact spring 241^a to disengage the contact spring 239^a, thereby to interrupt a further point in the circuit for energizing the switching relay R360. At this time, the finder switch 301 is completely released for further use.

When ground potential is removed from the control conductor C327 of the trunk line 325, the circuits for energizing the cut-off relays R340 and R660 in the line circuits 300 and 675, respectively, are interrupted, causing these relays to restore. Upon restoring, the cut-off relay R340 reconditions the line circuit 300 to control the connections of the substation A to the finder and connector switches having access thereto. 70 Upon restoring, the cut-off relay R660 reconditions the line circuit 675 to control the connections of the substation B to the finder and connector switches having access thereto. At this time the link 501 and the apparatus located at 75

the substations A and B are completely restored and available for further use.

Operation of the connector switch 500 to select P. B. X. trunk lines

5 In extending a call from the substation A to the private branch exchange 700 by way of the link 501 and one of the trunk lines extending to the private branch exchange or P. B. X., the operations of the distributor and common equipment 302, and the finder switch 301, are the same as previously described. Also, the initial operation of the connector switch 500 is the same as that previously described. In this case, three 10 digits corresponding to the private branch exchange directory number are successively dialed at the substation A, after the link 501 is seized, in order to cause the wipers 49^b, 50^b, 48^b and 51^b of the odd wiper set of the elementary switch illustrated 15 of the switching unit embodied in the connector switch 500 to engage the conductors 710, 711, 713 and 712, respectively, in the conductor bank 24, in a manner similar to that previously described. The conductors 710, 713, 711 20 and 712 in the conductor bank 24 are respectively connected to the line conductors C701 and C702, and the control conductors C703 and C704 of the first P. B. X. trunk line 705. Also, it is noted that the first digit dialed at the substation A in order 25 to cause operation of the connector switch 500 to seize the first P. B. X. trunk line extending to the private branch exchange 700, comprises an odd number of impulses, thereby to prevent the circuit for energizing the switching relay R600 from 30 being completed. As the switching relay R600 is not operated, the armatures RA601, RA604 and RA607 remain in engagement with the contacts RC602, RC605 and RC609, respectively. 35

The subsequent operation of the connector switch 500 depends upon the idle or busy condition of the P. B. X. trunk line 705. In the event the P. B. X. trunk line 705 is busy, ground potential appears upon the control conductors C703 and C704 thereof. The ground potential appearing upon the control conductor C703 causes the busy relay R570 to be energized over a circuit extending from the grounded control conductor C703 by way of the conductor 711, the wiper 50^b, RC605, RA604, RA562, RA563 and the winding 40 of R570 to battery. When energized over the above-traced circuit, the busy relay R570 operates in a manner similar to that previously explained. Upon operating, the busy relay R570 prepares at RA571' and RC572 its holding circuit 45 and completes at RA575 a circuit, traced hereinafter, for energizing the control relay R610. Also, the presence of ground potential upon the control conductor C704 causes the control relay R610 to be energized, after the control relay R540 restores, over a circuit extending from the grounded control conductor C704 by way of the conductor 712, the wiper 51^b, C624, RA575, the contact springs of the set 233^b, corresponding to the contact set 233 shown in Fig. 7, RA543, C638 and 50 the winding of R610 to battery. The contact set 233^b comprises two contact spring 234^b and 235^b of the self-interrupting type. When energized over the above-traced circuit, the control relay R610 operates to complete at RA611 a holding circuit for the control relay R560, this circuit extending from ground at RA611 by way of C639 and the winding of R560 to battery. The control relay R560 is held operated over the above-traced circuit to retain completed at RA562 and RA563 55 the original operating circuit of the busy relay 55 R570 and to retain completed at RA566 the first energizing circuit of the operating motor M^{1b}. Thus, the holding circuit of the busy relay R570 is not completed and the escapement control mechanism of the switching unit embodied in the connector switch 500 is not driven into its fourth off-normal position at this time. Also, upon operating, the control relay R610 completes at RA612 a circuit for energizing the operating motor M^{1b}, this circuit extending from ground at RA612 by way of C637 and the winding of M^{1b} to battery. When energized over the above-traced circuit, the operating motor M^{1b} operates to move the wipers 49^b, 50^b, 48^b and 51^b into engagement with other conductors in the conductor bank 24 which comprise a line connected to the second trunk line extending to the private branch exchange 700. Also, upon operating, the operating motor M^{1b} interrupts at the self-interrupting contact springs 234^b and 235^b the circuit 20 for energizing the control relay R610, and the latter relay restores. Upon restoring, the control relay R610 interrupts at RA611 the holding circuit of the control relay R560, and interrupts at RA612 the energizing circuit of the operating motor M^{1b}. When the energizing circuit of the operating motor M^{1b} is interrupted, the operating motor M^{1b} restores to prepare at the contact springs 234^b and 235^b a point in the circuit for energizing the control relay R610. If the second 25 trunk line extending to the private branch exchange 700 is busy, the circuit for energizing the control relay R610 is recompleted, causing this relay to reoperate and recomplete at RA611 the holding circuit of the control relay R560 before 30 the latter relay restores, and to recomplete at RA612 the energizing circuit of the operating motor M^{1b}. The control relay R610 and the operating motor M^{1b} continue to interact, as described above, until the wipers noted engage a line in the conductor bank 24 which is connected either to an idle P. B. X. line extending to the private branch exchange 700 or to the last P. B. X. trunk line extending to the private branch exchange 700. 35

In the event all of the P.B.X. trunk lines extending to the private branch exchange 700 are busy, the control relay R610 and the operating motor M^{1b} continue to interact until the wipers noted engage the line in the conductor bank 24 which is connected to the last busy P.B.X. trunk line extending to the private branch exchange 700. The control conductors of the last P.B.X. trunk line extending to the private branch exchange 700, and corresponding to the control conductors C703 and C704 of the P.B.X. trunk line 705, are not connected together, the control conductor corresponding to the control conductor C703 having ground potential appearing thereon, and the control conductor corresponding to the control conductor C704 being open-circuited. When the wipers noted engage the line in the conductor bank 24 connected to the last P.B.X. trunk line extending to the private branch exchange 700, the control relay R610 is 40 not reenergized as ground potential does not appear upon the control conductor of the last P.B.X. trunk line corresponding to the control conductor C704 of the P.B.X. trunk line 705. Thus, the control relay R610 is not reoperated 45 and shortly thereafter the control relay R560 restores to complete at RA563 and RC564 the holding circuit of the busy relay R570. The busy relay R570 then operates in the manner previously described to return busy tone current over 50 50

75

the loop extending to the calling substation A, thereby to indicate to the calling party that a connection to the private branch exchange 700 may not be immediately completed. Upon receiving busy tone, the calling party at the substation A may release the link 501 in the manner previously described. Also, upon restoring, the control relay R560 interrupts at RA566 the first circuit for energizing the operating motor M2^b, causing this motor to restore. Upon restoring the operating motor M2^b drives the escapement control mechanism of the switching unit embodied in the connector switch 500 into its fourth off-normal position, thereby to render inoperative the unit bar of the switching unit.

In the event that one of the P.B.X. trunk lines extending to the private branch exchange 700 is idle, further interaction of the control relay R610 and the operating motor M1^b is arrested when this P.B.X. line is selected by the switching unit embodied in the connector switch 500, and the switching-through relay R590 is operated. For example, in the event that the P.B.X. trunk line 705 is idle, the switching-through relay R590 is operated when the wipers noted engage the conductors 710, 711, 712 and 713 in the conductor bank 24. At this time, the switching-through relay R590 is energized when the control relay R560 restores, this circuit extending from battery at the lower terminal of the cut-off relay R720 by way of the winding of R720, the control conductor C703 of the P.B.X. trunk line 705, the conductor 711, the wiper 50^b, RC605, RA604, RA562, RC565, the lower winding of R590, RC573 and RA571' to the grounded control conductor C327. During these operations and prior to the restoration of the busy relay R570, the control relay R610 is short-circuited, this short-circuiting path extending from battery at the lower terminal of the winding of R720 by way of the winding of R720, the control conductor C704 of the P.B.X. trunk line 705, the conductor 712, the wiper 512, C624, RA575, the contact springs 234^b and 235^b, RA543, C638, and the winding of R610 to battery at the upper terminal thereof. Thus, the control relay R610 does not operate to complete the holding circuit of the control relay R560 and to complete the energizing circuit of the operating motor M1^b. When energized over the above-traced circuit, the switching-through relay R590 operates, as previously explained, to connect the control conductor C703 of the P.B.X. trunk line 705 to the grounded control conductor C327.

When the control conductor C703 is connected to the grounded control conductor C327, the cut-off relay R720 is energized in an obvious manner to cause operation thereof. Upon operating, the cut-off relay R720 interrupts at RA721 and RA722 points in the circuit for energizing the line relay R730, thereby to prevent operation of the line relay R730 when the call is answered at the private branch exchange 700 and the consequent seizure of the P.B.X. trunk line 705 by the finder switch of a link assigned thereto. The projection of ringing current over the P.B.X. trunk line 705 and the operations of the ring cut-off relay R580 and the battery reversing relay R550, when the call is answered at the private branch exchange 700, are the same as previously described. Also, the release of the established connection between the substation A and the private branch exchange 700 is under the control of the calling party at the substation A

and is performed in the manner previously described.

While there has been described what is at present considered to be the preferred embodiment of the invention, it will be understood that various modifications may be made therein, and it is contemplated to cover in the appended claims all such modifications as fall within the true spirit and scope of the invention.

What is claimed is:

1. In a signaling system, a plurality of divisions of lines each including two groups, and a line selecting switch comprising, in combination, a trunk line, a switching mechanism having access to each of said lines, means responsive to a first series of impulses for causing said switching mechanism to select one of said divisions of lines, means responsive to the character of said first series of impulses for electing one of the groups in said selected division of lines and for preparing said trunk line to be connected to any line in said elected group of lines, means operative in response to at least one additional series of impulses for causing said switching mechanism to seize two corresponding lines in the two groups in said selected division of lines, and means directly controlled by the operation of said last-mentioned means for connecting said trunk line to the seized line in said elected group of lines.

2. In a signaling system, a plurality of divisions of lines each including two groups, each of said groups including a plurality of subgroups of lines, and a line selecting switch comprising, in combination, a trunk line, a switching mechanism having access to each of said lines, means responsive to a first series of impulses for causing said switching mechanism to select one of said divisions of lines, means responsive to the character of said first series of impulses for electing one of the groups in said selected division of lines and for preparing said trunk line to be connected to any line in said elected group of lines, means responsive to a second series of impulses for causing said switching mechanism to select two corresponding subgroups in the two groups in said selected division of lines, means responsive to a third series of impulses for causing said switching mechanisms to seize two corresponding lines in said two selected subgroups of lines, and means controlled by said last-mentioned means for connecting said trunk line to the seized line in said selected subgroup in said elected group of lines.

3. In a signaling system, a plurality of divisions of lines each including two groups, and a line selecting switch comprising, in combination, a trunk line, a switching mechanism having access to each of said lines, said switching mechanism including two line selecting devices, means responsive to a first series of impulses for causing said switching mechanism to select one of said divisions of lines, means responsive to the character of said first series of impulses for electing one of said line selecting devices and for preparing said trunk line to be connected to said elected line selecting device, means operative in response to at least one additional series of impulses for operating said switching mechanism to cause said line selecting devices to seize two corresponding lines in the two groups in said selected division of lines, and means directly controlled by the operation of said last-mentioned means for connecting said trunk line to said elected line selecting device.

4. In a telephone system, a plurality of divisions

5 of lines each including two groups, and a finder switch comprising, in combination, a trunk line, a switching mechanism having access to each of said lines, said switching mechanism including two line selecting devices, means responsive to the presence of a calling condition on one of two corresponding lines in the two groups in one of said divisions of lines for initiating operation of said finder switch to cause said switching mechanism to select said one division of lines and to 10 prepare said trunk line to be connected to an elected one of said line selecting devices, means for causing said switching mechanism subsequently to operate said line selecting devices to 15 seize said two corresponding lines in the two groups in said selected division of lines, said one line being seized by said elected line selecting device, and means controlled by said last-mentioned means for connecting said trunk line to 20 said elected line selecting device.

6. In a signaling system, a plurality of divisions of lines each including two groups, and a line selecting switch comprising, in combination, a trunk line, a switching mechanism including a plurality of elementary switches individually associated with said divisions of lines, each of said elementary switches being operable independently of the other of said elementary switches and including two line selecting devices individually associated with the two groups of lines in the associated division, means for selecting any one of said elementary switches to be operated, means for operating a selected one of said elementary switches to cause the two line selecting devices thereof to seize two corresponding lines in the two associated groups in the division of lines associated with the selected elementary switch, and means for selectively connecting said trunk line to each one of said line selecting devices of said selected elementary switch.

7. In a signaling system, a plurality of divisions of lines each including two groups of lines, each of said groups including a plurality of subgroups of lines, and a line selecting switch comprising, in combination, a trunk line, a switching mechanism including a plurality of elementary switches individually associated with said divisions of lines, each of said elementary switches including two line selecting devices individually associated with the two groups of lines in the associated division, means including a first operating member for selecting any one of said elementary switches to be operated, thereby to select the associated divisions of lines, means including a second operating member for operating a selected one of said elementary switches to cause the two line selecting devices thereof to select any two corresponding subgroups of lines in the two associated groups in the previously selected division of lines, means including a third operating member for operating said selected elementary switch to cause the two line selecting devices thereof to seize any two corresponding lines in the previously selected subgroups of lines, means for rendering successively operative said first, second and third operating members, means for selectively operating an operative one of said operating members, means for controlling said two last-mentioned means, and means for selectively connecting said trunk line to each one of said line selecting devices of said selected elementary switch.

8. In a signaling system, a plurality of divisions of lines each including two groups, and a line selecting switch comprising, in combination,

trunk line, a switching mechanism including a plurality of elementary switches individually associated with said divisions of lines, each of said elementary switches being operable independently of the other of said elementary switches and including two line selecting devices individually associated with the two groups of lines in the associated division, impulse responsive means for selecting any one of said elementary switches to be operated, means for operating a selected one of said elementary switches to cause the two line selecting devices thereof to seize two corresponding lines in the two associated groups in the division of lines associated with the selected elementary switch, and means controlled by said impulse responsive means for selectively connecting said trunk line to each one of said line selecting devices of said selected elementary switch.

9. In a signaling system, a plurality of divisions of lines each including two groups, and a line selecting switch comprising, in combination, a trunk line, a switching mechanism including a plurality of elementary switches individually associated with said divisions of lines, each of said elementary switches being operable independently of the other of said elementary switches and including two line selecting devices individually associated with the two groups of lines in the associated division, means responsive to a first series of impulses for selecting one of said elementary switches to be operated, means responsive to at least one additional series of impulses for operating said selected elementary switch to cause the two line selecting devices thereof to seize two corresponding lines in the two associated groups in the division of lines associated with the selected elementary switch, means for selectively connecting said trunk line to each one of said line selecting devices of said selected elementary switch, and means responsive to the character of said first series of impulses for controlling said last-mentioned means.

10. In a signaling system, a bank of fixed contacts including a plurality of divisions each including two groups, and an automatic switch comprising, in combination, a trunk line, a switching mechanism including a plurality of elementary switches individually associated with said divisions of fixed contacts, each of said elementary switches being operable independently of the other of said elementary switches and including two movable contacts individually associated with the two groups of fixed contacts in the associated division, impulse responsive means for selecting any one of said elementary switches to be operated and for operating a selected one of said elementary switches to cause the two movable contacts thereof to engage two corresponding fixed contacts in the two associated groups in the division of fixed contacts associated with the selected elementary switch, and means controlled by said impulse responsive means for selectively connecting said trunk line to each one of said movable contacts of said selected elementary switch.

11. In a signaling system, a bank of fixed contacts including a plurality of divisions each including two groups, and an automatic switch comprising, in combination, a trunk line, a switching mechanism including a plurality of elementary switches individually associated with said divisions of fixed contacts, each of said elementary switches being operable independently of the other of said elementary switches and in-

- cluding two movable contacts individually associated with the two groups of fixed contacts in the associated division, two auxiliary lines respectively connected to corresponding ones of the 5 movable contacts of said elementary switches, impulse responsive means for selecting any one of said elementary switches to be operated and for operating a selected one of said elementary switches to cause the two movable contacts there-
- 10 of to engage two corresponding fixed contacts in the two associated groups in the division of fixed contacts associated with the selected elementary switch, and means controlled by said impulse responsive means for selectively connecting said 15 trunk line to each one of said auxiliary lines.
11. In a signaling system, a plurality of groups of lines each including a plurality of subgroups of lines, and a line selecting switch comprising, in combination, a switching mechanism including a 20 plurality of elementary switches individually associated with said groups of lines, means for selecting any one of said elementary switches to be operated, thereby to select the associated group of lines, means including an operating member 25 for causing a selected one of said elementary switches to select any one of the subgroups in the selected group of lines, means including another operating member for causing said selected elementary switch to select any one of the lines in 30 the selected subgroup of lines, a first impulse responsive means for rendering successively operative said first-mentioned and said second-mentioned operating members, a second impulse responsive means for selectively operating an operative one of said operating members, a circuit 35 for controlling said impulse responsive means, and control apparatus for said circuit, said control apparatus being so connected and arranged that during operation thereof a single control 40 impulse is transmitted by way of said circuit to said first impulse responsive means and a series of control impulses is thereafter transmitted by way of said circuit to said second impulse responsive means.
- 45 12. In a signaling system, a plurality of groups of lines each including a plurality of subgroups of lines, and a line selecting switch comprising, in combination, a switching mechanism including a plurality of elementary switches individually associated with said groups of lines, means including a first operating member for selecting any 50 one of said elementary switches to be operated, thereby to select the associated group of lines, means including a second operating member for 55 causing a selected one of said elementary switches to select any one of the subgroups in the selected group of lines, means including a third operating member for causing said selected elementary switch to select any one of the lines in the selected subgroup of lines, impulse responsive means for selectively and successively 60 operating said first, second and third operating members, a circuit for controlling said impulse responsive means, impulse transmitting apparatus, and means responsive to the presence of a calling condition on one of said lines for causing 65 said impulse transmitting device to transmit three series of control impulses by way of said circuit to said impulse responsive means, thereby to cause said first, second and third operating members to be selectively and successively operated to cause one of the elementary switches of said switching mechanism to seize said one line.
- 70 13. In a signaling system, a plurality of groups of lines each including a plurality of subgroups 75

of lines, and a line selecting switch comprising, in combination, a switching mechanism including a plurality of elementary switches individually associated with said groups of lines, three operating members supported for step-by-step movements, means responsive to the step-by-step movement of a first one of said operating members for selectively rendering said elementary switches operative, thereby to select the associated group of lines, means responsive to the step-by- 10 step movement of a second one of said operating members for selectively operating a selected one of said elementary switches to select a corresponding subgroup of lines in the selected group of lines, means responsive to the step-by- 15 step movement of a third one of said operating members for selectively operating further said selected elementary switch to select a corresponding line in the selected subgroup of lines, a first impulse responsive means for rendering successively operative said first, second and third operating members, a second impulse responsive means for selectively moving step by step an operative one of said operating members, a circuit for controlling said impulse responsive means, 20 and control apparatus for said circuit, said control apparatus being so connected and arranged that during operation thereof a single control impulse is transmitted by way of said circuit to said first impulse responsive means and a series 25 of control impulses is thereafter transmitted by way of said circuit to said second impulse responsive means.

14. In a telephone system, a plurality of groups of lines each including a plurality of subgroups of lines, and a finder switch comprising, in combination, a switching mechanism including a plurality of elementary switches individually associated with said groups of lines, means including a first operating member for selecting 35 any one of said elementary switches to be operated, thereby to select the associated group of lines, means including a second operating member for causing a selected one of said elementary switches to select any one of the subgroups in 45 the selected group of lines, means including a third operating member for causing said selected elementary switch to select any one of the lines in the selected subgroup of lines, impulse responsive means for selectively and successively 50 operating said first, second and third operating members, a circuit for controlling said impulse responsive means, impulse transmitting apparatus, and means responsive to the presence of a calling condition on one of said lines for causing 55 said impulse transmitting device to transmit three series of control impulses by way of said circuit to said impulse responsive means, thereby to cause said first, second and third operating members to be selectively and successively operated to cause one of the elementary switches of 60 said switching mechanism to seize said one line.

15. In a telephone system, a plurality of groups of lines each including a plurality of subgroups of lines, and a finder switch comprising, in combination, a switching mechanism including a plurality of elementary switches individually associated with said groups of lines, means including a first operating member for selecting 65 any one of said elementary switches to be operated, thereby to select the associated group of lines, means including a second operating member for causing a selected one of said elementary switches to select any one of the subgroups in 70

- the selected group of lines, means including a third operating member for causing said selected elementary switch to select any one of the lines in the selected subgroup of lines, impulse responsive means for selectively and successively operating said first, second and third operating members, a circuit for controlling said impulse responsive means, impulse transmitting apparatus, and means responsive to the presence of a calling condition on one of said lines for initiating operation of said impulse transmitting apparatus and for causing said impulse transmitting apparatus to transmit three series of control impulses respectively corresponding to the group of lines including said one line, to the subgroup of lines including said one line and to said one line by way of said circuit to said impulse responsive means, thereby to cause said first, second and third operating members to be selectively and successively operated to cause one of the elementary switches of said switching mechanism to seize said one line.
16. In a telephone system, a plurality of groups of lines each including a plurality of subgroups of lines, one of said groups of lines including at least one subgroup including a small group of lines, and a line selecting switch comprising, in combination, a switching mechanism having access to each of said lines, means including an impulse responsive magnet for operating said switching mechanism, first and second circuits for energizing said magnet, means for transmitting a plurality of series of impulses by way of said first circuit to said magnet to cause said switching mechanism to select one line in said small group of lines in said one subgroup in said one group of lines, means including a control relay for testing the idle or busy condition of a selected line in said small group of lines, said control relay being operated in the event the selected one line in said small group of lines is tested and found busy, and means responsive to the operation of said control relay for transmitting a single impulse by way of said second circuit to said magnet to cause said switching mechanism to select another line in said small group of lines.
17. In a telephone system, a plurality of groups of lines each including a plurality of subgroups of lines, one of said groups of lines including at least one subgroup including a small group of lines, and a line selecting switch comprising, in combination, a switching mechanism having access to each of said lines, means including an impulse responsive magnet for operating said switching mechanism, first and second circuits for energizing said magnet, means for transmitting a plurality of series of impulses by way of said first circuit to said magnet to cause said switching mechanism to select one line in said small group of lines in said one subgroup in said one group of lines, means including a control relay for testing the idle or busy condition of a selected line in said small group of lines, said control relay being operated in the event the selected one line in said small group of lines is tested busy, means responsive to the operation of said control relay for transmitting a single impulse by way of said second circuit to said magnet to cause said switching mechanism to select another line in said small group of lines, means responsive to the operation of said magnet for causing said control relay to restore, said control relay being reoperated in the event the selected other line in said small group of lines is tested busy, and means responsive to the test of a busy condition of the selected other line in said small group of lines for projecting busy tone current over said trunk line.
18. In a telephone system, a plurality of groups of lines each including a plurality of subgroups of lines, one of said groups of lines including at least one subgroup including a small group of lines, and a line selecting switch comprising, in combination, a trunk line, a switching mechanism having access to each of said lines, means including an impulse responsive magnet for operating said switching mechanism, first and second circuits for energizing said magnet, means for transmitting a plurality of series of impulses by way of said first circuit to said magnet to cause said switching mechanism to select one line in said small group of lines in said one subgroup in said one group of lines, means including a control relay for testing the idle or busy condition of a selected line in said small group of lines, said control relay being operated in the event the selected one line in said small group of lines is tested busy, means responsive to the operation of said control relay for transmitting a single impulse by way of said second circuit to said magnet to cause said switching mechanism to select another line in said small group of lines, means responsive to the operation of said magnet for causing said control relay to restore, said control relay remaining restored in the event the selected other line in said small group of lines is tested idle, and means responsive to the test of an idle condition of the selected other line in said small group of lines for connecting said trunk line thereto.
19. In a telephone system, a plurality of groups of lines each including a plurality of subgroups of lines, one of said groups of lines including at least one subgroup including a small group of lines, and a line selecting switch comprising, in combination, a trunk line, a switching mechanism having access to each of said lines, means including an impulse responsive magnet for operating said switching mechanism, first and second circuits for energizing said magnet, means for transmitting a plurality of series of impulses by way of said first circuit to said magnet to cause said switching mechanism to select one line in said small group of lines in said one subgroup in said one group of lines, means including a control relay for testing the idle or busy condition of a selected line in said small group of lines, said control relay being operated in the event the selected one line in said small group of lines is tested busy, means responsive to the operation of said control relay for transmitting a single impulse by way of said second circuit to said magnet to cause said switching mechanism to select another line in said small group of lines, means responsive to the operation of said magnet for causing said control relay to restore, said control relay remaining restored in the event the selected other line in said small group of lines is tested busy, means responsive to the operation of said control relay for transmitting a single impulse by way of said second circuit to said magnet to cause said switching mechanism to select another line in said small group of lines, means responsive to the operation of said magnet for causing said control relay to restore, said control relay remaining restored in the event the selected other line of said small group is tested busy, and means responsive to the test of a busy condition of the selected other line in said small group of lines for projecting busy tone current over said trunk line.
20. In a telephone system, a plurality of groups of lines each including a plurality of subgroups of lines, one of said groups of lines including at least one subgroup including a small group of lines, and a line selecting switch comprising, in

combination, a trunk line, a switching mechanism having access to each of said lines, means including an impulse responsive magnet for operating said switching mechanism, first and second circuits for energizing said magnet, means for transmitting a plurality of series of impulses by way of said first circuit to said magnet to cause said switching mechanism to select one line in said small group of lines in said one subgroup in said one group of lines, a busy relay, a first circuit for testing the idle or busy condition of a selected line in said small group and for energizing said busy relay, a control relay, a second circuit for testing the idle or busy condition of a selected line in said small group and for energizing said control relay, means responsive to the selection by said switching mechanism of the one line in said small group of lines for completing said first and second circuits and for causing operation of said busy and control relays in the event the selected one line is tested busy, and means responsive to the operation of said control relay for transmitting a single impulse by way of said second circuit to said magnet to cause said switching mechanism to select another line in said small group of lines, and means responsive to the operation of said magnet for interrupting said first and second circuits.

21. In a telephone system, a plurality of groups of lines each including a plurality of subgroups of lines, one of said groups of lines including at least one subgroup including a small group of lines, and a line selecting switch comprising, in combination, a trunk line, a switching mechanism having access to each of said lines, means including an impulse responsive magnet for operating said switching mechanism, first and second circuits for energizing said magnet, means for transmitting a plurality of series of impulses by way of said first circuit to said magnet to cause said switching mechanism to select one line in said small group of lines in said one subgroup in said one group of lines, a busy relay, a first circuit for testing the idle or busy condition of a selected line in said small group and for energizing said busy relay, a control relay, a second circuit for testing the idle or busy condition of a selected line in said small group and for energizing said control relay, means responsive to the selection by said switching mechanism of the one line in said small group of lines for completing said first and second circuits and for causing operation of said busy and control relays in the event the selected one line is tested busy, means responsive to the operation of said control relay for transmitting a single impulse by way of said second circuit to said magnet to cause said switching mechanism to select another line in said small group of lines, means responsive to the operation of said magnet for interrupting said first and second circuits, means responsive to the selection by said switching mechanism of the other line in said small group of lines for recompleteing said first and second circuits and for causing reoperation of said busy and control relays in the event the selected other line is tested busy, and means responsive to the reoperation of said control relay for transmitting another single impulse by way of said second circuit to said magnet to cause said switching mechanism to select a further line in said small group of lines.

22. In a telephone system, a plurality of groups of lines each including a plurality of subgroups of lines, one of said groups of lines including at least one subgroup including a small group of

lines, and a line selecting switch comprising, in combination, a trunk line, a switching mechanism having access to each of said lines, means including an impulse responsive magnet for operating said switching mechanism, first and second circuits for energizing said magnet, means for transmitting a plurality of series of impulses by way of said first circuit to said magnet to cause said switching mechanism to select one line in said small group of lines in said one subgroup 10 in said one group of lines, a busy relay, a first circuit for testing the idle or busy condition of a selected line in said small group and for energizing said busy relay, a control relay, a second circuit for testing the idle or busy condition of a 15 selected line in said small group and for energizing said control relay, means responsive to the selection by said switching mechanism of the one line in said small group of lines for completing said first and second circuits and for causing operation of said busy and control relays in the event the selected one line is tested busy, means responsive to the operation of said control relay for transmitting a single impulse by way of said second circuit to said magnet to cause said 20 switching mechanism to select another line in said small group of lines, means responsive to the operation of said magnet for interrupting said first and second circuits, means responsive to the selection by said switching mechanism of the 25 other line in said small group of lines for re-completing said first and second circuits and for preventing reoperation of said busy and control relays in the event the selected other line is tested idle, and means responsive to the test of an 30 idle condition of the selected other line in said small group of lines for connecting said trunk line thereto. 35

23. In a telephone system, a plurality of groups of lines each including a plurality of subgroups of lines, one of said groups of lines including at least one subgroup including a small group of lines, and a line selecting switch comprising, in combination, a trunk line, a switching mechanism having access to each of said lines, means including an impulse responsive magnet for operating said switching mechanism, first and second circuits for energizing said magnet, means for transmitting a plurality of series of impulses by way of said first circuit to said magnet to cause said switching mechanism to select one line in said small group of lines in said one subgroup in said one group of lines, a busy relay, a first circuit for testing the idle or busy condition of a selected line in said small group and for energizing said busy relay, a control relay, a second circuit for testing the idle or busy condition of a selected line in said small group and for energizing said control relay, means responsive to the selection by said switching mechanism of the one line in said small group of lines for completing said first and second circuits and for causing operation of said busy and control relays in the event the selected one line is tested busy, means responsive to the operation of said control relay for transmitting a single impulse by way of said second circuit to said magnet to cause said switching mechanism to select another line in said small group of lines, means responsive to the operation of said magnet for interrupting said first and second circuits, means responsive to the selection by said switching mechanism of the other line in said small group of lines for re-completing said first circuit and for causing re-operation of said busy relay in the event the 75

selected other line is tested busy, and means responsive to the reoperation of said busy relay for projecting busy tone current over said trunk line.

24. In a telephone system, a plurality of groups of lines each including a plurality of subgroups of lines, one of said groups of lines including at least one subgroup including a small group of lines, and a line selecting switch comprising, in combination, a switching mechanism including a plurality of elementary switches individually associated with said groups of lines, three operating members common to said elementary switches, means for operating a first one of said operating members to cause one of said elementary switches to select said one group of lines, means for operating a second one of said operating members to cause said one elementary switch to select said one subgroup in said one group of lines, means for operating a third one of said operating members to cause said one elementary switch to select one line in said small group in said one subgroup of lines, means for testing the idle or busy condition of a selected line in said small group of lines, and means responsive to the test of a busy condition of the selected one line in said small group of lines for operating said third operating member to cause said one elementary switch to select another line in said small group of lines.

25. In a telephone system, a plurality of groups of lines each including a plurality of subgroups of lines, one of said groups of lines including at least one subgroup including a small group of lines, and a line selecting switch comprising, in combination, a trunk line, a switching mechanism associated with said trunk line and including a plurality of elementary switches individually associated with said groups of lines, three operating members common to said elementary switches, means for operating a first one of said operating members to cause one of said elementary switches to select said one group of lines, means for operating a second one of said operating members to cause said one elementary switch to select said one subgroup in said one group of lines, means for operating a third one of said operating members to cause said one elementary switch to select one line in said small group in said one subgroup of lines, means for testing the idle or busy condition of a selected line in said small group of lines, and means responsive to the test of a busy condition of the selected one line in said small group of lines for operating said third operating member to cause said one elementary switch to select another line in said small group of lines, and means responsive to the test of a busy condition of the selected other line in said small group of lines for projecting busy tone current over said trunk line.

26. In a telephone system, a plurality of groups of lines each including a plurality of subgroups of lines, one of said groups of lines including at least one subgroup including a small group of lines, and a line selecting switch comprising, in combination, a trunk line, a switching mechanism associated with said trunk line and including a plurality of elementary switches individually associated with said groups of lines, three operating members common to said elementary switches, means for operating a first one of said operating members to cause one of said elementary switches to select said one group of lines, means for operating a second one of said operating members to cause said one elementary switch to select another line in said small group of lines, and means for operating a third one of said operating members to cause said one elementary switch to select said one subgroup in said one group of lines.

lines, means for operating a third one of said operating members to cause said one elementary switch to select one line in said small group in said one subgroup of lines, means for testing the idle or busy condition of a selected line in said small group of lines, means responsive to the test of a busy condition of the selected one line in said small group of lines for operating said third operating member to cause said one elementary switch to select another line in said small group of lines, and means responsive to the test of an idle condition of the selected other line in said small group of lines for connecting said trunk line thereto.

27. In a signaling system, a group of lines including a plurality of subgroups, an impulse responsive line selecting switch including a switching mechanism having access to each of said lines, a circuit for transmitting operating impulses to said switch, a stepping mechanism, means for causing said stepping mechanism to take a plurality of steps, said steps being divided into a plurality of active and inactive groups, successive groups of active steps being separated from each other by a group of inactive steps, said stepping mechanism being so constructed and arranged that said active steps are taken at one speed and said inactive steps are taken at a different speed, and means for transmitting by way of said circuit to said switch a plurality of series of operating impulses corresponding to the number of groups of active steps taken by said stepping mechanism, the number of impulses in each of said series corresponding to the number of steps taken by said stepping mechanism in the corresponding group of active steps, thereby to cause said switching mechanism to select a corresponding line in a corresponding subgroup in said group of lines.

28. In a signaling system, a group of lines including a plurality of subgroups, an impulse responsive line selecting switch including a switching mechanism having access to each of said lines, a circuit for transmitting operating impulses to said switch, a stepping mechanism, means including a motor for operating said stepping mechanism a plurality of steps, said steps being divided into a plurality of active and inactive groups, successive groups of active steps being separated from each other by a group of inactive steps, a circuit for energizing said motor, means for controlling said energizing circuit to cause said motor to operate said stepping mechanism said active steps at a relatively low speed and to operate said stepping mechanism said inactive steps at a relatively high speed, and means for transmitting by way of said first-mentioned circuit to said switch a plurality of series of operating impulses corresponding to the number of groups of active steps said stepping mechanism is operated, the number of impulses in each series corresponding to the number of steps said stepping mechanism is operated in the corresponding group of active steps, thereby to cause said switching mechanism to select a corresponding line in a corresponding subgroup in said group of lines.

29. In a signaling system, a group of lines including a plurality of subgroups, an impulse responsive line selecting switch including a switching mechanism having access to each of said lines, a circuit for transmitting operating impulses to said switch, a stepping mechanism, means including a motor for operating said stepping mechanism a plurality of steps, said steps being divided

info a plurality of active and inactive groups, successive groups of active steps being separated from each other by a group of inactive steps, a circuit for energizing said motor, control apparatus including a slow acting relay for said energizing circuit, said control apparatus being so connected and arranged that said motor operates said stepping mechanism said active steps at a relatively low speed and operates said stepping mechanism said inactive steps at a relatively high speed, and means controlled by said control apparatus for transmitting by way of said first-mentioned circuit to said switch a plurality of series of operating impulses corresponding to the number of groups of active steps said stepping mechanism is operated, the number of impulses in each series corresponding to the number of steps said stepping mechanism is operated in the corresponding group of active steps, thereby to cause said switching mechanism to select a corresponding line in a corresponding subgroup in said group of lines.

30. In a signaling system, a group of lines including a plurality of subgroups, an impulse responsive line selecting switch including a switching mechanism having access to each of said lines, a circuit for transmitting operating impulses to said switch, a stepping mechanism, means including an impulse responsive motor for operating said stepping mechanism a plurality of steps, said steps being divided into a plurality of active and inactive groups, successive groups of active steps being separated from each other by a group of inactive steps, a circuit for energizing said motor, control apparatus for transmitting control impulses by way of said energizing circuit to said motor to cause said motor to operate said stepping mechanism step by step, said control apparatus being so connected and arranged that the control impulses are transmitted to said motor at a relative low rate to cause said motor to operate said stepping mechanism said active steps and at a relatively high rate to cause said motor to operate said stepping mechanism said inactive steps, and means controlled by said control apparatus for transmitting by way of said first-mentioned circuit to said switch a plurality of series of operating impulses corresponding to the number of groups of active steps said stepping mechanism is operated, the number of impulses in each series corresponding to the number of steps said stepping mechanism is operated in the corresponding group of active steps, thereby to cause said switching mechanism to select a corresponding line in a corresponding subgroup in said group of lines.

31. In a signaling system, a group of lines including a plurality of subgroups, an impulse responsive line selecting switch including a switching mechanism having access to each of said lines, a circuit for transmitting operating impulses to said switch, a stepping mechanism, means including an impulse responsive motor for operating said stepping mechanism a plurality of steps, said steps being divided into a plurality of active and inactive groups, successive groups of active steps being separated from each other by a group of inactive steps, a circuit for energizing said motor, control apparatus including a plurality of relays for transmitting control impulses by way of said energizing circuit to said motor to cause said motor to operate said stepping mechanism step by step, said control apparatus also including means controlled by the operation of said stepping mechanism for selectively controlling

said relays, thereby to control the rate at which control impulses are transmitted to said motor, said control apparatus being so connected and arranged that the control impulses are transmitted to said motor at a relatively low rate to cause said motor to operate said stepping mechanism said active steps and at a relatively high rate to cause said motor to operate said stepping mechanism said inactive steps, and means controlled by said control apparatus for transmitting by way of said first-mentioned circuit to said switch a plurality of series of operating impulses corresponding to the number of groups of active steps said stepping mechanism is operated, the number of impulses in each series corresponding to the number of steps said stepping mechanism is operated in the corresponding group of active steps, thereby to cause said switching mechanism to select a corresponding line in a corresponding subgroup in said group of lines.

32. In a telephone system, a group of lines including a plurality of subgroups, an impulse responsive finder switch including a switching mechanism having access to each of said lines, a circuit for transmitting operating impulses to said switch, a stepping mechanism associated with said lines and operative to take a plurality of steps divided into a plurality of active and inactive groups, successive groups of active steps being separated from each other by a group of inactive steps, said stepping mechanism being so constructed and arranged that said active steps are taken at one rate and said inactive steps are taken at a different rate, means responsive to the creation of a calling condition on one of the lines in one of the subgroups in said group of lines for initiating operation of said stepping mechanism and for causing said stepping mechanism to take a plurality of groups of active and inactive steps, the number of groups of active steps including at least two, the number of active steps in one of said groups corresponding to said one subgroup and the number of active steps in the other of said groups corresponding to said one line, and means for transmitting by way of said circuit to said switch a plurality of series of operating impulses corresponding to the number of groups of active steps taken by said stepping mechanism, the number of impulses in each of said series corresponding to the number of steps taken by said stepping mechanism in the corresponding group of active steps, thereby to cause said switch mechanism to seize said one line.

33. In a telephone system, a group of lines including a plurality of subgroups, an impulse responsive finder switch including a trunk line and a switching mechanism having access to each of said lines, a circuit for transmitting operating impulses to said switch, a stepping mechanism associated with said lines and operative to take a plurality of steps from a normal position, said steps being divided into a plurality of active and inactive groups, successive groups of active steps being separated from each other by a group of inactive steps, said stepping mechanism being so constructed and arranged that said active steps are taken at one speed and said inactive steps are taken at a different speed, means responsive to the creation of a calling condition on one of the lines in one of the subgroups in said group of lines for initiating operation of said stepping mechanism and for causing said stepping mechanism to take a plurality of groups of active and inactive steps, the number of groups of active steps including at least two, the number of ac- 75

tive steps in one of said groups corresponding to said one subgroup and the number of active steps in the other of said groups corresponding to said one line, means for transmitting by way of said circuit to said switch a plurality of series of operating impulses corresponding to the number of groups of active steps taken by said stepping mechanism, the number of impulses in each of said series corresponding to the number of steps taken by said stepping mechanism in the corresponding group of active steps, thereby to cause said switching mechanism to seize said one line, means responsive to the seizure of said one line for connecting said trunk line thereto, and means responsive to the connection of said trunk line to said one line for releasing and operating said stepping mechanism back into its normal position.

34. In a signaling system, a plurality of groups of lines each including a plurality of subgroups of lines, and a line selecting switch comprising, in combination, a switching mechanism including a plurality of elementary switches individually associated with said groups of lines, means including a first operating member for selecting any one of said elementary switches to be operated, thereby to select the associated group of lines, means including a second operating member for causing a selected one of said elementary switches to select any one of the subgroups in the selected group of lines, means including a third operating member for causing said selected elementary switches to select any one of the lines in the selected subgroup of lines, each of said operating members having a normal and a plurality of off-normal positions corresponding respectively to idle and operated positions thereof, means for moving said operating members in a predetermined order from their normal into their off-normal positions, a reset mechanism for moving said operating members in a different predetermined order from their off-normal back into their normal positions, a motor for operating said reset mechanism, and means under the joint control of at least one of said operating members and said reset mechanism for controlling said motor.

35. In a signaling system, a plurality of groups of lines each including a plurality of subgroups of lines, and a line selecting switch comprising, in combination, a switching mechanism including a plurality of elementary switches individually associated with said groups of lines, means including a first operating member for selecting any one of said elementary switches to be operated, thereby to select the associated group of lines, means including a second operating member for causing a selected one of said elementary switches to select any one of the subgroups in the selected group of lines, means including a third operating member for causing said selected elementary switches to select any one of the lines in the selected subgroup of lines, each of said operating members having a normal and a plurality of off-normal positions corresponding respectively to idle and operated positions thereof, means for moving said operating members in a different predetermined order from their normal into their off-normal positions, a reset mechanism for moving said operating members in a different predetermined order from their off-normal back into their normal positions, a motor for operating said reset mechanism, and means responsive to a predetermined operation of said reset mechanism for completing one of said circuits, means responsive to a predetermined operation of said reset mechanism for completing the other of said circuits, means responsive to a predetermined operation of said reset mechanism for interrupting one of said circuits, and means responsive to a predetermined operation of said reset mechanism for interrupting the other of said circuits.

36. In a signaling system, a plurality of groups of lines each including a plurality of subgroups of lines, and a line selecting switch comprising, in combination, a switching mechanism including a plurality of elementary switches individually associated with said groups of lines, means including a first operating member for selecting any one of said elementary switches to be operated, thereby to select the associated group of lines, means including a second operating member for causing a selected one of said elementary switches to select any one of the subgroups in the selected group of lines, means including a third operating member for causing said selected elementary switches to select any one of the lines in the selected subgroup of lines, each of said operating members having a normal and a plurality of off-normal positions corresponding respectively to idle and operated positions thereof, means for moving successively said first, second and third operating members from their normal positions into their off-normal positions, a reset mechanism for moving said third operating member from its off-normal position back into its normal position and then for moving said second and first operating members from their off-normal back into their normal positions, a motor for operating said reset mechanism, and means under the joint control of at least one of said operating members and said reset mechanism for controlling said motor.

37. In a telephone system, a plurality of groups of lines, a number of finder switches, each of said finder switches having access to each of said lines, a plurality of distributors individually associated with said groups of lines, each of said distributors having access to each of said finder switches and comprising automatic means for selecting an idle one of said finder switches, normally effective control means individually associated with said groups of lines and responsive to the presence of a calling condition on any one of the lines in the associated one of said groups of lines for initiating operation of the associated one of said distributors and for marking said one line in said one group of lines, means responsive to the operation of said one distributor for rendering ineffective the control means associated with said one group of lines, means controlled by the operation of said one distributor for causing the finder switch selected thereby to seize said one marked line in said one group of lines, and means controlled when said one marked line in said one group of lines is seized for arresting operation of said one distributor and for again rendering effective the control means associated with said one group of lines.

38. In a telephone system, a plurality of groups of lines, relays individually associated with said lines, the relays associated with each of said groups of lines being provided with operating circuits including a common point, each of said relays being provided with a holding circuit, a number of finder switches, each of said finder switches having access to each of said lines, a plurality of distributors individually associated with said groups of lines, each of said distributors having access to each of said finder switches and comprising automatic means for selecting

to the movement of at least one of said operating members back into its normal position for interrupting one of said circuits, and means responsive to another predetermined operation of said reset mechanism for interrupting the other of said circuits.

39. In a telephone system, a plurality of groups of lines, a number of finder switches, each of said finder switches having access to each of said lines, a plurality of distributors individually associated with said groups of lines, each of said distributors having access to each of said finder switches and comprising automatic means for selecting an idle one of said finder switches, normally effective control means individually associated with said groups of lines and responsive to the presence of a calling condition on any one of the lines in the associated one of said groups of lines for initiating operation of the associated one of said distributors and for marking said one line in said one group of lines, means responsive to the operation of said one distributor for rendering ineffective the control means associated with said one group of lines, means controlled by the operation of said one distributor for causing the finder switch selected thereby to seize said one marked line in said one group of lines, and means controlled when said one marked line in said one group of lines is seized for arresting operation of said one distributor and for again rendering effective the control means associated with said one group of lines.

40. In a telephone system, a plurality of groups of lines, relays individually associated with said lines, the relays associated with each of said groups of lines being provided with operating circuits including a common point, each of said relays being provided with a holding circuit, a number of finder switches, each of said finder switches having access to each of said lines, a plurality of distributors individually associated with said groups of lines, each of said distributors having access to each of said finder switches and comprising automatic means for selecting

41. In a telephone system, a plurality of groups of lines, relays individually associated with said lines, the relays associated with each of said groups of lines being provided with operating circuits including a common point, each of said relays being provided with a holding circuit, a number of finder switches, each of said finder switches having access to each of said lines, a plurality of distributors individually associated with said groups of lines, each of said distributors having access to each of said finder switches and comprising automatic means for selecting

- an idle one of said finder switches, normally effective means responsive to the presence of a calling condition on any one of the lines in any one of said groups of lines for completing the 5 operating circuit of the associated one of said relays, thereby to cause said one relay to operate, means responsive to the operation of said one relay for completing the holding circuit of said one relay and for interrupting the common point 10 in the operating circuits of said relays, means controlled by the operation of said one relay for initiating operation of the one of said distributors associated with said one group of lines and for marking said one line in said one group of lines, 15 means controlled by the operation of said one distributor for causing the finder switch selected thereby to seize said one marked line in said one group of lines, and means controlled when said one marked line in said one group of lines is 20 seized for interrupting a further point in the operating circuit and the holding circuit of said one relay and for preparing the common point in the operating circuits of the other of said relays associated with the lines in said one group of 25 lines.
39. In a switching system including a contact bank; a plurality of switching units commonly associated with said contact bank; each of said switching units being operable independently of the other of said switching units and comprising a plurality of independently operable elementary switches; each of said elementary switches including a carriage movable in a first direction with respect to said contact bank, an element 30 carried by said carriage and movable in a second direction with respect to said contact bank, and a contact controlling member carried by said element; means for selecting any one of said switching units to be operated; means for selecting any one of the elementary switches of said 35 selected switching unit to be operated; and means for moving the carriage and the element of said selected elementary switch of said selected switching unit.
40. In a switching system including a contact bank divided into a plurality of divisions of contacts; a plurality of switching units commonly associated with said contact bank; each of said switching units comprising a plurality of elementary switches respectively associated with the 40 divisions of contacts in said contact bank; each of said switching units being operative independently of the other of said switching units; each of the elementary switches of a switching unit being operative independently of the other of the elementary switches of the switching unit to control the contacts in the associated division of contacts in said contact bank; means for selecting any one of said switching units to be operated; means for selecting any one of the elementary 45 switches of said selected switching unit to be operated; and means for selectively controlling the operation of said selected elementary switch of said selected switching unit.
41. In a switching system including a contact bank divided into a plurality of divisions of contacts, each of said divisions of contacts being divided into two groups of contacts; a plurality of switching units commonly associated with said contact bank; each of said switching units comprising a plurality of elementary switches respectively 50 associated with the divisions of contacts in said contact bank, each of said elementary switches including two contact control devices respectively associated with the two groups of contacts in the associated division of contacts in said contact bank; each of said switching units being operative independently of the other of said switching units; each of the elementary switches of a switching unit being operative independently of the other of the elementary switches of the switching unit to cause the two contact control devices thereof to control the contacts in the respective groups of contacts in the associated division of contacts in said contact bank; means for selecting any one of said switching units to be 55 operated; means for selecting any one of the elementary switches of said selected switching unit to be operated; and means for selectively controlling the operation of said selected elementary switch of said selected switching unit.
42. In a signaling system comprising a plurality of divisions of lines each including a number of groups of lines; a switching unit comprising a plurality of elementary switches respectively having access to said divisions of lines, each of said elementary switches being selectively operable independently of the other of said elementary switches to seize any line in a selected group of lines in the associated division of lines, impulse responsive means controlled by a single series of 60 impulses for selecting any one of said elementary switches to be operated and for selecting any one of the groups of lines in the division of lines associated with said selected elementary switch, and additional impulse responsive means for selectively controlling the operation of said selected elementary switch.
43. In a signaling system comprising a plurality of divisions of lines each including a number of groups of lines; a switching unit having access to said lines and comprising a mechanically movable member, impulse responsive means for selectively moving said member, mechanical means governed by the movement of said member for selecting any one of said divisions of lines, and electrical means governed by the movement of said member for selecting any one of the groups of lines in said selected division of lines.
44. In a signaling system comprising a plurality of divisions of lines each including two groups of lines; a switching unit comprising a plurality of elementary switches respectively associated with said divisions of lines, each of said elementary switches being operable independently of the other of said elementary switches and including two line selecting devices respectively associated with the two groups of lines in the associated division of lines, a mechanically movable member, impulse responsive means for selectively moving said member, means governed by the movement of said member for selecting any one of said elementary switches to be operated, thereby to select the corresponding one of said divisions of lines, and means including electrical contacts governed by the movement of said member for selecting one of the line selecting devices of said selected elementary switch, thereby to select a corresponding group of lines in said selected division of lines.
